UNITED STATES PATENT OFFICE

RUDOLPH F. STEHLIK, OF CHICAGO, ILLINOIS, ASSIGNOR TO AUTOMATIC ELECTRIC INC.,
OF CHICAGO, ILLINOIS, A CORPORATION OF DELAWARE

MULTIOFFICE TELEPHONE SYSTEM

Application filed July 19, 1926. Serial No. 123,323. Renewed February 27, 1929.

The present invention relates to multi-office telephone systems, but more particularly to multi-office telephone systems containing both automatic offices and manual offices.

The principal object of the invention is the production of suitable circuit arrangements such that the organizations of equipment that are known as directors, and are used to control the operation of the automatic switches, may be used also to transmit series of coded impulses to operate the call indicators in the manual offices.

A further object of the invention is the production of suitable circuit arrangements whereby the combination directors send call indicator impulses representing subscriber digits only in case the call is to a terminating manual office reached directly from an automatic office, and send, prior to the sending of the subscriber digit impulses, suitable call indicator impulses indicative of the particular called manual office when the call is completed to or through a tandem manual office.

In accordance with a further object of the invention, arrangements are provided whereby the talking conductors, at any repeater or trunk holding circuits at which the talking conductors are inductively coupled, are connected together metallically and cleared of their bridges prior to the sending of the call indicator impulses so as to permit the call indicator impulses to be delivered from the combination directors directly to the call indicator equipment in the manual office, and suitable arrangements are provided for again cutting in the repeaters and the trunk holding circuits after the call indicator impulses have passed through.

There are quite a number of objects and features which are more or less subsidiary to the foregoing main object. These latter objects and features are listed below:

(a) A feature of the invention relates to the provision of suitable arrangements whereby the digits transmitted in code to the call indicator at a tandem manual office may be assigned at will by making suitable cross connections in the director.

(b) A further feature more or less closely connected with the one in the preceding

paragraph relates to the novel arrangement whereby the regular sender of the director, which is used ordinarily to transmit impulse series to set the automatic switches, is transformed automatically at the proper time during a tandem manual office call so that it functions under the control of the register on which the office digits are recorded to set the registers that are to transmit the call indicator digits indicative of the particular manual office called.

(c) According to a further feature of the invention, when the call is for a manual office, the regular sender of the director operates in the usual manner to trunk the call forward toward its designation until a trunk line leading to the manual office is reached, but the operator is not signalled responsive to the seizure of the trunk line. When, however, all the registers in the director have been set the director exerts a further controlling influence on the holding circuit to cause the operator to be signalled.

(d) A further feature resides in the arrangement involving the trunking cord circuits at tandem manual offices and the call indicators at such offices. The arrangement is such that the ringing circuit in the cord circuit is rendered effective by the call indicator if the setting of the indicator is such as to indicate that the call is a local call, the ringing circuit being such that it is ineffective otherwise.

(e) According to still another feature of the invention, arrangements have been provided whereby the indicator sender of the director is caused to automatically skip over the office-digit positions when the call is for a terminating manual office reached directly from an automatic office, so as to enable the call indicator sender to send subscriber digits only.

(f) Another feature of the invention relates to arrangements employed for automatically terminating the cut-through condition of the repeaters and the trunk holding circuits after the call indicator impulses have been transmitted, so as to permit a release of the connection.

There are other objects and features of the

invention in addition to the ones mentioned specifically hereinbefore which can be understood best from a perusal of the following description in connection with the accompanying drawings. Referring now to the drawings comprising Figs. 1-13 showing circuit diagrams and Fig. 14 showing a layout of Figs. 1-13, Figs. 1-4 show the trunking equipment used in setting up certain connections; Fig. 5, shows the call indicator at a tandem manual office; Figs. 6-10, show the combination director; and Figs. 11-13, show certain desirable modifications.

More in detail, Fig. 1 shows a trunk comprising conductors 5-7 extending from the line switch banks 2-4 to the selector S-1. The trunk circuit TC-1 is inserted in this trunk for the purpose of controlling the director (of which there is a plurality) which may be connected to the trunk by means of the director selector DS. The trunk circuit TC-1 is arranged to supply talking current to the calling line and to hold up the switches in the calling automatic office so that repeaters on the outgoing trunks are unnecessary.

Fig. 2 shows the second selector S-2 on the incoming end of the inter-office trunk comprising conductors 75 and 76, together with the repeater R-1 associated with the trunk comprising conductors 135 and 136 outgoing to the third automatic office. This drawing shows also the timer T-1 that comes into play, when the talking conductors at the repeater R-1 are switched straight through, to terminate the switched-through condition after a suitable interval has been allowed to elapse.

Fig. 3 shows the trunk holding circuit TC-2, on the outgoing end of the trunk line comprising conductors 241 and 242 extending to a manual office. This holding circuit is inserted between the banks of the selector S-3 and the outgoing conductors of the trunk line in order to provide a holding circuit for the selector S-3 and in order to maintain the bridge across the conductors 241 and 242 leading to the manual office open after the seizure of the trunk line and until the trunk circuit is controlled from the director to close the bridge so as to signal the operator.

Fig. 4 shows the cord circuit CC-1 on the incoming end of the trunk comprising conductors 241 and 242. This drawing shows also the cord circuit CC-2 on the incoming end of a trunk line connecting the tandem manual office with the terminating manual office. The cord circuit CC-1 is used to complete the connection to a line local to the tandem manual office if the call is for such line, and to extend the connection to a terminating manual office in case the call is for a line in such office.

Fig. 5 shows the six-digit call indicator that may be associated with any of the cord circuits

in the tandem manual office to indicate the called office and to indicate the number of the subscriber in such office. The relays 409-411 are the receiving relays; relays 401 and 402 are switching relays that switch the contacts of the receiving relays to the four relay-operating conductors in regular rotation as each digit is received; the two rows of relays lying above the center of the sheet are the transfer relays; and the relays below the center of the sheet are the registering relays. The first two groups of the registering relays register the two code digits indicative of the called office, and the remaining four groups of registering relays register the thousands, hundreds, tens, and units digits of the number of the called line.

The relay 304 of the cord circuit CC-1 Fig. 4, is energized over conductor 357 from the call indicator shown in Fig. 5, in case the call is for a line terminating in the tandem manual office. Relay 304 operates to adapt the cord circuit CC-1 so that ringing current will be sent out in the usual manner when the plug of the cord circuit is inserted into the jack of the called line.

Referring now to Figs. 6-10 which show the combination director, the portion of the director shown in Fig. 6, includes the input-control sequence switch S and the output-control sequence switch S', together with the relays 521 and 522 that control the sequence switch S.

Fig. 7 shows the release relay 622 which is energized over the release trunk conductor 37 when the director is seized; the switching relay 621 which is operated at the end of the transmission of the number to bring about the switching-through operation at the trunk circuit, and the freeing of the director; relay 623 is the sending relay of the director that controls the sending of the stepping impulses that operate the automatic switches and is in turn controlled by the interrupter 626; relay 624 is the pick-up relay that operates at the beginning of the transmission of a series of impulses; and relay 625 is the stop relay that is operated through the stop wiper 649 of the sending switch SS to terminate the digit being transmitted.

In Fig. 8, the office register OR registers the two office digits of any called number and brings its wipers 725 into engagement with the set of bank contacts assigned to the called office. The intermediate distributing frame I.D.F. is provided in order to permit the control exercised by the office register OR on the sending equipment of the director to be assigned or varied at will.

Fig. 9, shows the thousands, hundreds, tens, and units registers that register the subscriber digits of the number, and it shows also the code registers CR-1 and CR-2 that are set in accordance with the position of the office register OR by the regular sender when the call is completed to or through a tandem man-

ual office. The upper wiper of each of the thousands, hundreds, tens and units registers is for the purpose of controlling the regular sending switch SS Fig. 7, and the two lower wipers of each of these registers, as well as the two lower wipers of each of the code registers

5 CR-1 and CR-2 are for the purpose of controlling the call indicator sender SS' Fig. 10.

Considering now the equipment shown in Fig. 10, relay 901 is pulled up when the setting of the office register OR Fig. 8, indicates that the call is completed to or through a tandem manual office; relay 902 is similarly pulled up, instead of relay 901, if the call is to be completed to a terminating manual office reached directly from an automatic office; relays 903 and 904 send the impulse that is repeated at the repeater R-1 to the trunk circuit TC-2 to cause the operator to be signalled when all 15 the registers have been set; relays 905-907 are for the purpose of securing the starting of the code sending switch SS' when the operator responds; and relay 908 is the relay that closes the restoring circuit of the sender SS' 20 in case the same is in an off-normal position when the release of the director occurs.

In Fig. 11, a portion of the director shown in Figs. 6-10, is shown with a certain modification to be hereinafter explained. The 25 trunk circuit TC-3 may be used in place of a trunk circuit TC-1 Fig. 1, in case repeaters are used on the outgoing trunk lines, as it is then unnecessary to incorporate a holding arrangement in the trunk circuit ahead of 30 the first selector.

The repeater R-2, Fig. 12, is used to replace the repeater R-1 Fig. 2, when the director is modified as in Fig. 11.

The holding circuit TC-4, Fig. 13, is used 40 to replace the holding circuit TC-2, Fig. 3, when the modified director is used.

The invention having been described generally, a detailed description of the operation of the apparatus shown will now be given.

45 For this purpose it will be explained first how the director handles a call that is completed to a subscriber of an automatic exchange, and for the sake of simplicity it will be assumed that the called line terminates in the same 50 exchange as the calling line.

Call to automatic line

Assuming that the line switch of a calling subscriber who desires to call an automatic 55 subscriber seizes the trunk line comprising conductors 5-7 at the terminals 2-4, line relay 10 pulls up over the calling line and closes at armature 15 a circuit for release relay 11. Release relay 11 grounds the release trunk

60 conductor 6 at armature 17 so as to provide a holding circuit for the calling line switch. It will be observed that the grounding of conductor 6 results in the closure of a circuit through the left hand winding of the electro- 65 polarized relay 8. Owing to the fact that the

cores of the two windings of the relay 8 are connected together by the soft iron yokes as shown, the relay 8 is not operated at this time because the core of the right hand winding serves as a shunt around the core of the left hand winding. 70

As a further result of the operation of relay 11, a circuit is closed at armature 18 for relay 26 of the director selector DS in series with the stepping magnet 25, and at armature 19 the junction of the relay and magnet is connected through armature 23 and the resting contact and armature 29 to the test wiper 33. If the director on which the wipers of the director selector DS are standing is idle, relay 26 pulls up without being affected by the connection to the test wiper, but, if the director is busy, a ground potential is encountered by test wiper 33. In this case relay 26 is short circuited and stepping magnet 25 operates in the usual buzzer-like manner to advance the wipers of the switch DS step-by-step in search of an idle director. When an idle director is reached, for example, the one shown in Figs. 6-10, 90 the stepping action of the selector DS ceases, and relay 26, being no longer short circuited, pulls up in series with stepping magnet 25. Stepping magnet 25 does not operate at this time on account of the relatively high resistance of relay 26. Upon operating, relay 26 disconnects test wiper 33 from the test circuit and connects it to ground at armature 29, thereby making the seized director busy immediately; prepares the impulse circuit at 95 armature 30; and at armatures 27 and 28 connects the conductors 5' and 7' extending to the selector S-1 to the loop conductors 35 and 36 of the director. When this occurs, line relay 51 of the selector S-1 pulls up over conductors 35 and 36 through the resting contacts and armatures 635 and 738 Fig. 7, conductor 604 and the resting contact and armature 919, Fig. 10. At armature 62, relay 51 closes a circuit for relay 52, which prepares the switch for operation at armature 64 and places an additional ground on conductor 6' at armature 63. 100

In the seized director, release relay 622 Fig. 7, pulls up over the release trunk conductor 37 when conductor 37 is grounded upon the seizure of the director and opens the normal restoring circuit of the sending switch SS at armature 631; opens the restoring circuit, including conductor 507, of the sequence switch S' at armature 633; at armature 634 removes ground from the release conductor 502; and at armature 632 places ground on conductor 608, whereupon the release relay 908, Fig. 10, of the sending switch SS' operates to open the normal restoring circuit of the sending switch SS' and to prepare at armature 936 and its working contact a switch-through circuit over the conductor 110 607. 115

In the seized director, release relay 622 Fig. 7, pulls up over the release trunk conductor 37 when conductor 37 is grounded upon the seizure of the director and opens the normal restoring circuit of the sending switch SS at armature 631; opens the restoring circuit, including conductor 507, of the sequence switch S' at armature 633; at armature 634 removes ground from the release conductor 502; and at armature 632 places ground on conductor 608, whereupon the release relay 908, Fig. 10, of the sending switch SS' operates to open the normal restoring circuit of the sending switch SS' and to prepare at armature 936 and its working contact a switch-through circuit over the conductor 120 607. 125

The calling subscriber may now dial the first digit in the desired number, and, when he does so, line relay 10, of the trunk circuit TC—1 Fig. 1, falls back once for each interruption produced in the line circuit at the calling substation. Each time it falls back, it closes at armature 16 a circuit through armature 30 and its working contact, wiper 34, the bank contact on which it is standing, conductor 38, armature 627, Fig. 7, and its resting contact, conductor 505, distributing wiper 527 and its first contact, the associated conductor, and vertical magnet 727 of the office register OR to battery. By the operation of the vertical magnet, the wipers of the office register OR are raised step-by-step and they come to rest opposite the desired level of bank contact.

Series relay 521, Fig. 6, operates upon the transmission of the first impulse of current to the vertical magnet, and, being slow acting, remains operated throughout the series of impulses. At its upper armature relay 521 closes a circuit for relay 522 which operates and prepares a circuit for stepping magnet 523 of the switch S. This circuit is closed momentarily when relay 521 falls back at the end of the series of impulses, and the circuit is opened again by relay 522 when it falls back. The result is a momentary energization of stepping magnet 522 to advance the wipers 526 and 527 one step. When the second office digit is dialled, the impulses of current are delivered over the circuit path above traced to wiper 527, Fig. 6. From this point, the impulses of current are delivered through the conductor terminating in the second bank contact of wiper 527 to the rotary magnet 726 of the office register OR. By the operation of the rotary magnet, the wipers of the office register OR are rotated step-by-step until they come to rest upon the desired set of contacts, which set of bank contacts, it will be assumed, is the set bearing the reference numeral 721.

When the wipers of the sequence switch S are advanced another step at the end of the rotary movement of the office register OR, the distributing wiper 527 extends the impulse conductor to the conductor leading to the stepping magnet of the thousands register, Fig. 9. At the same time, wiper 526 of the switch S connects ground to the start conductor extending to the first six contacts in the bank of wiper 530. This results in the starting of the regular sender shown in Fig. 7 to transmit the code of the called office in a manner to be explained hereinafter.

When the calling subscriber dials the thousands digit, the thousands-digit register shown in Fig. 9 is operated to register such digit; the hundreds register registers the hundreds digits when it is dialled; the tens register registers the tens digit; and the units register registers the units digit,

the wipers 526 and 527 of the sequence switch S, Fig. 6, being advanced one step at the end of each digit in the manner above described. At the end of the units digit, wiper 527 encounters a dead bank contact and the sequence switch S remains in this position until the director is released.

Returning now to the point at which the start conductor extending to the first six bank contacts of the wiper 530, Fig. 6, is grounded upon the advance of wiper 526 into its third position at the end of the second office digit, the ground potential is extended by wiper 530 of the sequence switch S' to the impulse conductor 509, closing a circuit through the resting contact and armature 644 and the interrupter 626 for the sending relay 623. Relay 623 now energizes and de-energizes under the control of the interrupter 626. Upon its first energization, relay 623 closes at armature 636 a circuit for stepping magnet 647 of the sending switch SS. Magnet 647 operates and moves the associated pawl into engagement with the next tooth in the wiper driving ratchet wheel, but does not advance the wipers 648 and 649. At armature 635, relay 623 opens a point in the outgoing control circuit including conductors 35 and 36, but this is without effect at this time as armature 635 and its resting contact is shunted at the resting contact and armature 638. When relay 623 falls back the first time, it permits magnet 647 to fall back and advance the wipers one step, whereupon pick-up relay 624 is operated through wiper 648. At armature 638 relay 624 removes the shunt from around the sending contacts 635, and at armature 639 it prepares a locking circuit for relay 625 and closes, through armature 643 and its resting contact, a circuit over conductor 506 for magnet 528 of the sequence switch S'. Magnet 528 operates over this circuit preparatory to advancing the wipers 529 and 530.

As the shunt is now removed from around the sending contacts 635 of relay 623, each subsequent operation of relay 623 opens the outgoing control circuit momentarily, wipers 648 and 649 being advanced an additional step at the termination of each opening in such circuit. As the call is for a subscriber local to the calling exchange, and as the local thousands selectors are accessible from the third level of the selector S—1, Fig. 1, the first contact in the group 721 on which the wipers of the office register OR, Fig. 8, are now standing is cross connected on the I. D. F. to the third impulse stop conductor, and, when the wiper 649 encounters the third impulse stop conductor at the end of the third interruption in the outgoing control circuit, stop relay 625 is operated over the following circuit: from ground by way of wiper 531, Fig. 6, the first associated bank contact, the upper wiper of the office register OR, the

bank contact on which it is standing, the associated I. D. F. jumper, the third impulse stop conductor, the associated contact in the bank of wiper 649, Fig. 7, and relay 625 to battery. At armature 644, relay 625 disconnects relay 623 before it has had time to operate again; it closes the restoring circuit of the sending switch SS at armature 642; and at armature 643 it closes a locking circuit for itself through the working contact and armature 639, at the same time removing ground from conductor 506. Magnet 528 of the sequence switch S' now falls back and advances the wipers 529—531 one step, and wiper 531 removes ground from the first wiper of the office register OR and places it, on the second wiper. Since one code digit is sufficient in the present case, it is necessary that the remaining code-digit positions of the sequence switch S' be skipped automatically without any digits being sent corresponding to such positions. Accordingly, the bank contacts on which the remaining wipers of the office register OR are standing, are cross connected to the skip conductor 501. The skip conductor 501 is connected through the self-interrupting contacts of magnet 528, Fig. 6 to the said magnet. The result is that magnet 528 operates in its usual buzzer-like manner and advances the wipers 529—531 until the last code-digit position of the switch S' has been passed, and the wipers have landed in their seventh position, corresponding to the thousands digit.

When the restoring circuit of the sending switch SS is closed at armature 642 of stop relay 625, magnet 647 operates through its self-interrupting contacts and advances the wipers 648 and 649 to their normal position, in which position the restoring circuit is opened at the wiper 648, as is the circuit of pick-up relay 624. Relay 624 is slow acting and it remains operated for an interval after its circuit is opened.

After the interval for which it is adjusted, relay 624 falls back and opens at armature 639 the locking circuit of relay 625. Relay 625 is slow acting also, and it remains operated for another interval, after which it also falls back and again connects up the interrupter 626 at armature 644 to start the transmission of the next digit (in this case the thousands digit). It may be pointed out that the interval required for relays 624 and 625 to fall back one after the other is sufficiently long to permit a selector to initiate and effect its trunk hunting movement before the next digit is transmitted.

As the wiper 531 of the sequence switch S' is now on its seventh bank contact which is connected to the upper wiper of the thousands register, Fig. 9, the thousands digit, which is started when the stop relay 625 falls back as above described, is terminated in accordance with the setting of the thousands register; the

hundreds digit is terminated in accordance with the setting of the hundreds register; the tens digit is terminated in accordance with the setting of the tens register; and the units digit is terminated in accordance with the setting of the units register, the wipers of the sequence switch S' being advanced automatically one step at the end of each digit and in the manner above described. That being the case, wiper 531 reaches its last position upon being advanced another step at the end of the unit digit, and it places ground on the switch-through conductor 508 in order to bring about the switch-through operation in the trunk circuit TC' and the freeing of the director in the manner to be described subsequently.

Considering now the effect of the transmission of the digits on the automatic switches, line relay 51 of the selector S—1 falls back once for each of the three interruptions produced in its circuit when the office code digit 3 is transmitted by the director. Each time it falls back, relay 51 closes at armature 62 a circuit through armature 64 and its working contact and relay 53 for the vertical magnet 59. Vertical magnet 59 operates in the usual manner and raises the wipers 72—74 step-by-step opposite the first level of bank contacts. The slow acting series relay 53 operates when the first impulse is transmitted and it remains operated until after the third impulse has been transmitted. At armature 65, relay 53 closes a circuit in conjunction with the off-normal contacts 61, which operated upon the first vertical step, through the interrupter contacts 60, for stepping relay 54. Relay 54 operates over this circuit and closes a locking circuit for itself at armature 66. At armature 67 it prepares a circuit for rotary magnet 58.

When relay 53 falls back shortly after the end of the third impulse, it closes the rotary magnet circuit at armature 65, whereupon rotary magnet 58 operates and advances the wipers of the selector into engagement with the first bank contact in the third level. Near the end of its stroke, magnet 58 opens the stepping relay circuit at the interrupter contacts 60. Stepping relay 54 falls back and opens the rotary magnet circuit, whereupon the rotary magnet falls back and closes its interrupter contacts 60 again.

From this point on, the operation depends upon whether the first trunk line is busy or is idle. If this trunk line is idle, switching relay 55 now operates, seizing the trunk. If the trunk is busy, however, relay 55 is short circuited and relay 54 is again operated by the ground potential encountered on the test contact of the busy trunk by test wiper 73. Relay 54, therefore, again closes the rotary magnet circuit, and the wipers are advanced another step.

This alternate operation of relay 54 and 130

magnet 58 continues in the manner described until an idle trunk is reached, which trunk, it may be assumed, is the one connected to the set of bank contacts shown from which conductors extend, according to the label, to a local thousands selector. When this idle trunk line is reached, relay 55 energizes in series with relay 54, but relay 54 is not operated at this time on account of the relatively high resistance of relay 55. At armature 70, relay 55 removes ground from armature 62 of line relay 51, thereby opening the circuit of release relay 52 and preventing any further operation of the vertical magnet 59 and any operation of release magnet 57 until relay 55 again falls back; it opens the test circuit and connects test wiper 73 to the grounded release trunk conductor 6', thereby making the seized trunk busy immediately; and at armatures 68 and 71 it disconnects conductors 5' and 7' from the windings of line relay 51 and extends them through wipers 72 and 74, and the bank contacts on which they are standing to the line relay of the seized thousands selector. The line and release relays (not shown) now operate in the usual manner to prepare the switch for operation and to place a further ground on the release trunk conductor of the partly established connection. A moment later relay 52 falls back and removes ground from conductor 6' at armature 63, but this is of no effect at this time as the release trunk conductor is already grounded at two other points.

When the thousands digit is transmitted by the director, the seized thousands selector operates in the usual manner to extend the connection to a hundreds selector in the desired group, the seized hundreds selector operates when the hundreds digit is transmitted and extends the connection to an idle connector in the desired group; and the seized connector operates in response to the tens and units digits transmitted by the director and extends the connection to the called line and applies ringing current thereto in the usual manner.

Returning now to the director, when wiper 531 of the sequence switch S' grounds the conductor 508 at the end of the transmission of the units digit, the two windings of the two step relays 621 Fig. 7, are energized in series, operating the relay. At armature 627 relay 621 disconnects conductor 38 from conductor 505 and connects it to ground, thereby closing a circuit over conductor 38 and through wiper 34, working contact and armature 30, and armature 16 and its working contact for switching relay 12. Relay 12 energizes and locks itself to the release trunk conductor 6' at armature 21, releases the switch DS at armatures 22 and 23, and at armatures 20 and 24 connects the two sections of the trunk line together between the trunk circuit TC-1 and the selector S-1. Now, when relay 26 of

director selector DS falls back due to the opening of its circuit at armature 22 it disconnects conductors 5' and 7' from the conductors 35 and 36 extending to the director, leaving the line relay of the connector involved in the connection held up through armatures 20 and 24, right hand winding of relay 8, and the impedance 9. Relay 8 is not operated at this time, however, on account of the fact that the direction of current in the right hand winding of relay 8 is such that the magneto-motive force generated by the said winding assists the flow of magnetism in its original path, each core of the relay serving as a shunt for the other.

In the director, relay 622, Fig. 7, falls back when the director is freed by the director selector DS, Fig. 1. At armature 631, relay 622 closes the normal restoring circuit of the sending switch SS; it closes the restoring circuit of the switch S' at armature 633, whereupon the switch S' advances the remaining step to its normal position; and at armature 634 it places ground on conductor 502. When this occurs, the release magnets of the switches S and OR Figs. 6 and 8, and the release magnets of the thousands, hundreds, tens, and units registers of Fig. 9, operate through their respective off-normal contacts to release the said switches in the usual manner. For example, magnet 522 of the switch S Fig. 6, is operated through off-normal contacts 525, and the release magnet 728 of the office register OR is operated through off-normal contacts 729.

When the called subscriber responds to the ringing of his bell by removing his receiver, the connector switch in use cuts off the ringing current and substitutes talking current, whereupon the current flow in the calling conductors extending to the connector switch is reversed by the connector switch in the usual manner. When this occurs, the current flow in the right hand winding of relay 8, Fig. 1, is reversed, and the magnetism generated by both windings in multiple now operates the relay. At armatures 13 and 14, relay 8 reverses conductors 5 and 7 as regards their connection to the windings of relay 10, thereby reversing the current flow in the calling line. This may be made use of to operate a meter for any other similar purpose.

Referring now again to the director, the arrangement for supplying ground to the impulse conductor 509, after the wiper 530 of the sequence switch S' has advanced beyond the positions in which ground is supplied from the start conductor, will now be explained. Ground potential is supplied to the seventh and eighth contacts in the bank of wiper 530 over conductor 503, which is grounded through the upper off-normal contacts of the hundreds register when the hundreds register goes off-normal, ground being supplied to these off-normal contacts over

conductor 811 and through armatures 909 and 914, Fig. 10 for a purpose to be explained hereinafter. It will be appreciated, therefore, that, if the hundreds register has not gone off-normal when the wipers of the sequence switch arrive in the position in which the thousands digit is sent, no ground is present on the impulse conductor 509 and the sending operation is delayed until the hundreds register goes off-normal. This arrangement prevents the sender from attempting to send the thousands and hundreds digits before they are registered. In a similar way the sending operation may again be held up when the sequence switch arrives in the position in which the tens digit is sent if the units register has not gone off-normal to supply ground to the ninth and tenth contacts of the bank of wiper 530 over conductor 504.

When the conversation between the calling and called parties has taken place and has been terminated, the two parties replace their receivers. When the receiver is replaced at the called substation, the back-bridge battery-feed relay of the connector falls back and reverses the current flow to normal in the talking conductors incoming to the connector. When this occurs, relay 8, Fig. 1, falls back and reverses the incoming conductors 5 and 7 back to the position shown in the drawing.

When the calling subscriber replaces his receiver, line relay 10 falls back and at its upper armature opens the bridge across the conductors 5' and 7', whereupon the line relay of the connector falls back and opens the circuit of the associated release relay. At armature 13, relay 10 opens the circuit of relay 11, which falls back after an interval and removes at armature 17 the ground potential from the associated release trunk conductor. This operation, however, is of no effect until the ground potential is removed from the release trunk conductor of the established connection at the connector switch in use. When such removal of ground potential takes place on the falling back of the release relay of the connector, the thousands and hundreds selectors release responsive to the removal of ground potential, and the connector switch is released in the usual manner. In the trunk circuit TC-1 the switching relay 12 falls back and relay 55 falls back in the selector S-1, the usual circuit through off-normal contacts 56 is closed for release magnet 57 at armature 70 of relay 55. The calling line switch releases in the usual manner when ground is removed from the release trunk conductor.

Call through tandem manual office

Assuming now that a calling subscriber, desiring to converse with the subscriber at the substation 356, Fig. 4 removes his re-

ceiver; that the trunk line shown in Fig. 1 is seized by the calling line switch; and that the director selector DS seizes the director shown in the drawings; the director is prepared for operation in the usual manner when relay 622 Fig. 7 pulls up, and the setting of the office register OR occurs when the first two digits are dialled. Following the setting of the office register, the four subscriber digit registers shown in Fig. 9, are set in the manner hereinbefore described.

It is assumed that the terminating manual office in which the line of substation 356 Fig. 4 terminate is represented by the bank contacts 723, Fig. 8. It will be observed that the call must be trunked to the tandem manual office, Fig. 4, and that three code digits are necessary to operate the selectors S-1, Fig. 1, S-2, Fig. 2, and S-3, Fig. 3, these digits being 1, 3, and 8. Accordingly, the first bank contact in the set 723 Fig. 8 is cross connected on the I. D. F. to the first impulse stop conductor; the second bank contact is cross connected to the eighth impulse stop conductor; and the third bank contact is cross connected to the third impulse stop conductor. Accordingly, the code digits 1, 3, and 8 are transmitted in the hereinbefore described manner when the sending switch SS is started at the end of the second office digit, the sequence switch S' being advanced one step at the end of each digit. Since the combination director must now operate in a different manner to handle this call, which is of a different class, relay 901, Fig. 10 must now be operated. This relay is operated responsive to the arrival of wiper 531 Fig. 6, in the fourth position responsive to the transmission of the third and last code digit 8, the circuit being as follows: From ground by way of the now-grounded fourth wiper of the office register OR, the fourth contact in the set 723, the associated I. D. F. jumper, conductor 701, normally-closed contacts controlled by armature 912, Fig. 10, and relay 901 to battery. Upon operating, relay 901 locks itself at armature 912 to the grounded conductor 608, at the same time opening its initial circuit. At armature 913, relay 901 connects conductor 701 with the conductor 702. Conductor 702 terminates in a terminal at the I. D. F., Fig. 8, and is cross connected in the I. D. F. to the skip conductor 501. This results in the operation of the switch S' Fig. 6 to now pass over the fourth code-digit position and come to rest in the fifth code digit position. As a further result of its operation, relay 901, Fig. 10, prepares at armature 911 a circuit for relay 903; joins conductors 35 and 604 at armature 910, so as to shunt the sending contacts 635, Fig. 7, to prevent further impulses from the regular sender from going out; and at armature 909 it removes ground from conductor 607 for a purpose to be hereinafter made clear, and it

applies ground to conductor 606 to enable the code registers CR-1 and CR-2, Fig. 9, to be operated by the regular sender SS, Fig. 7, under the control of the office register OR as will now be pointed out.

- 5 It will be noted that the fifth bank contact in the set 723, Fig. 8, is cross-connected to the fifth impulse stop conductor and that the sixth bank contact is cross-connected to 10 the fourth impulse stop conductor. This is done so that the code registers CR-1 and CR-2 Fig. 9 will be set in their fifth and fourth positions respectively in order to control the sending of call indicator impulses 15 which will bring in the code number 54 on the call indicator shown in Fig. 5, when the call indicator is subsequently operated.

After the third regular code digit has been terminated, relays 624 and 625 fall back after 20 the usual interval and the sending relay 623 starts operating again in the usual manner. Pick-up relay 624 pulls up upon the first step of the sending switch SS, but the removal of the shunt from around the sending 25 contacts 635 is of no avail at this time, as the said contacts are now shunted, as above pointed out, at armature 910, Fig. 10. Conductor 606, however, is now grounded at armature 909, Fig. 10, and the operation of relay 624 30 serves to prepare an impulse circuit including the said conductor 606 and armature 640 of pick-up relay 624. Accordingly, upon each energization of relay 623, following the energization of pick-up relay 624, a circuit is 35 closed from the grounded conductor 606, through the working contact and armature 637, armature 640 and its working contact, and the armature 645 and its resting contact to conductor 610. The first of these impulses 40 is delivered over conductor 610, through the contact of off normal spring 803 and said spring, and series relay 801 to the stepping magnet 804 of the code register CR-1. By the operation of the stepping magnet, the 45 associated wipers are driven around to the position corresponding to the number of impulses received. Relay 801 operates when the first impulse is received, and, being slow-acting, remains operated throughout the 50 series of impulses. At armature 802 this relay opens a point in the circuit of stepping magnet 805 and prepares the impulsing circuit over a new path so as to maintain its own circuit and that magnet 804 intact after the 55 off-normal springs of the register have shifted, as they do upon the first step. Since the cross connection at the I. D. F. Fig. 8, is such that the fifth bank contact in the set now being used is cross connected to the fifth 60 impulse stop conductor, the sending operation continues until five impulses have been delivered to the stepping magnet 804, and then the stop relay 625 of the sender is operated in the usual manner over the fifth impulse stop 65 conductor. During the interval between the

digit 5 and the following digit, relay 801 falls back and at armature 802 shifts the associated impulse circuit to the magnet 805. The result is that the next digit, the digit 4 which is sent with the wipers of the sequence switch S' in their sixth positions, is delivered to the stepping magnet 805 Fig. 9. This results in the wipers of the code register CR-2 being set in their fourth position.

When the sequence switch S' advances 75 from its sixth position to its seventh position at the end of the transmission of the series of impulses to the code register CR-2 Fig. 9, the impulse circuit is opened by wiper 530, as the impulse conductor 509 is disconnected 80 from the start conductor and is connected to conductor 503. Conductor 503 is not grounded at this time regardless of whether the hundreds register, Fig. 9, is off-normal or not, as the conductor 811 that supplies ground to the lower spring of the upper pair of off-normal contacts of the hundreds register is ungrounded at armature 909 of relay 901, Fig. 10. Accordingly no further operation 85 of the regular sender can take place during this call. Before the operation of the director is considered further the effect of the transmission of the three code digits 1, 3, and 90 8 will now be considered.

Responsive to the transmission of the first 95 code digit 1, the selector S-1 Fig. 1, operates in the usual manner to place its wipers opposite the first level of bank contacts and seize an idle trunk line outgoing to the automatic office #2. Assuming that the trunk line comprising conductors 75 and 76 is the one seized, the incoming selector S-2 Fig. 2, is prepared for operation in the usual manner, and it responds to the second code digit 3 and raises its wipers opposite the third level and 100 searches for an idle trunk line. Assuming that the trunk line extending to the repeater R-1 and comprising conductors 104-106 is the first one found to be idle, line relay 109 energizes over conductors 104 and 106, when the trunk line is seized, and closes a circuit 105 for release relay 110 at armature 120.

Release relay 110 closes at armature 125 a circuit for the polarizing winding of the electro-polarized relay 108; prepares a circuit 110 for relay 113 at armature 124; places ground on release trunk conductor 105 at armature 123 so as to maintain the selector S-2 operated and to maintain the trunk line busy; and at armature 122 it completes a bridge 115 across conductors 135 and 136 that was prepared at armature 121 of line relay 109. This bridge includes relay 114 and the left hand winding of relay 108 in addition to the normally closed contact controlled by armatures 116 and 117. When this bridge is closed, the selector S-3 on the distant end of the trunk line is prepared for operation in the usual manner.

When the third and last regular code digit 120

8 is transmitted, line relay 109 of the repeater R-1 falls back once for each interruption in its circuit. Each time it falls back, line relay 109 at armature 121 opens the bridge across the conductors 135 and 136, thereby bringing about the operation of the selector S-3 Fig. 3, in the usual manner. At armature 120, relay 109 closes a circuit each time it falls back through the working contact and armature 124 and the resting contact and armature 128 for relay 113. Relay 113 is slow acting, and, when it operates the first time, it remains operated throughout the digit. At armature 131, relay 113 closes the bridge across conductors 135 and 136 by a new path that excludes relay 114 and the left hand winding of relay 108. At armature 132 relay 113 opens a point in the circuit of the stiffly adjusted relay 112 so as to prevent the operation of this relay at this time, which would otherwise occur due to the fact that relay 114 is deenergized during the transmission of impulses.

At the end of the series of impulses, line relay 109 comes to rest in an energized condition, and relay 113 shortly falls back and shifts the bridge back to its original path including relay 114, whereupon relay 114 operates again and prevents the operation of relay 112.

In the third automatic exchange, the selector S-3 responds to the digit 8 and raises its wipers opposite the eighth level and rotates them in search of an idle trunk line. Assuming that the trunk line extending to the trunk circuit TC-2 and comprising conductors 207-209 is the first one found to be idle, this trunk line is seized, and line relay 212 energizes over conductors 207 and 209. At armature 223, relay 212 closes a circuit for release relay 213, and relay 213 at armature 226 closes a circuit for the polarizing winding of relay 221 at armature 226 and grounds the release trunk conductor 208 at armature 225. It is to be noted that no bridge is closed across conductors 241 and 242 responsive to the seizure of the trunk circuit TC-2, as it is desired to delay the signalling of the operator until all the registers in the director have been set.

Returning now to the director, a circuit is prepared at armature 646 when the stop relay 625 pulls up at the end of the digit transmitted to set the code register CR-2. After an interval, relay 624 falls back and at armature 641 shunts the working contact and armature 646 so that the circuit will remain intact after both the pick-up and stop relays have fallen back. This circuit, it will be noted, includes the bottom off-normal contacts of the code register CR-2 and also the off-normal contact of the units register, as well as the resting contact and lower armature of series relay 521 Fig. 6. Accordingly, when the units register has been set, or when

the code register CR-2, Fig. 9, has been set, whichever is completed last, relay 903, Fig. 10, energizes over the following circuit: from ground by way of the upper off-normal contacts of the units register, Fig. 9, conductor 504, lower armature of relay 521, Fig. 6, and its resting contact, conductor 510, either the working contact and armature 646 or the resting contact and armature 641 (depending upon the time at which the circuit is initially completed), conductor 609, lower off-normal contacts of the code register CR-2, Fig. 9, conductor 806, armature 911 and its working contact, Fig. 10, and relay 903 to battery. At armature 920, relay 903 closes a circuit for the slow-to-pull-up relay 904, and at armature 919 opens the bridge across the conductors 35 and 36. When this bridge is opened, the line relay 109 of the repeater R-1, Fig. 2, falls back and opens the bridge across conductors 135 and 136 at armature 121. When this occurs, relay 212 of the trunk circuit TC-2, Fig. 3, falls back, and at armature 223 closes a circuit through armature 227 and its working contact, 231 and its resting contact, armature 234 and its resting contact, for the lower winding of relay 217. Relay 217 operates and at armature 237 closes a bridge across conductors 241 and 242 through the normally closed contacts controlled by armatures 218 and 220 and through armature 237 and its working contact and its own upper winding. The current flow over conductors 241 and 242 is now able to maintain relay 217 operated through its upper winding independent of the lower winding. At armature 236, relay 217 closes a circuit from ground through armature 226 and its working contact, armature 229 and its resting contact, and armature 236 and its working contact for relay 216. Relay 216 is energized and at armature 233 closes a locking circuit for itself; prepares a circuit for relay 210 at armature 232; and at armature 234 opens the circuit of the lower winding of relay 217, leaving relay 217 locked energized through its upper winding.

In the manual office, Fig. 4, line relay 302 energizes over conductors 241 and 242 and in series with the upper winding of relay 217, Fig. 3, and closes at armature 312 a circuit through the resting contact and armature 322 for the combination answer and disconnect lamp 307. This lamp accordingly becomes lighted to inform the operator of the call.

In the director, the slow-to-pull-up relay 904, whose circuit was closed at armature 920 by relay 903 when the latter relay interrupted the outgoing control circuit at armature 919, pulls up after a slight interval and at armature 922 closes a circuit through armature 928 and its resting contact for the upper winding of relay 907. Relay 907 operates and at armature 932 closes a new bridge across con-

ductors 604 and 36 to replace the path formerly closed through the resting contact and armature 919. This new bridge includes armatures 925 and 926 of relay 905 and their resting contacts, armature 932 and its working contact, and the lower winding of relay 907. The lower winding of relay 907 now energizes in series with the line relay of the repeater R—1 Fig. 1, so as to maintain the relay operated independent of the upper winding. At armature 933, relay 907 closes a circuit from the grounded conductor 608 for relay 906. Relay 906 operates and locks itself to conductor 608 at armature 929; prepares a circuit for relay 905 at armature 930; and at armature 928 opens the circuit of the upper winding of relay 907, leaving the said relay energized over to its lower winding.

In the repeater R—1, Fig. 2, line relay 109, upon operating again after its momentary deenergization, again closes the circuit of release relay 110 at armature 120 and opens the circuit of the series relay 113, at the same time reclosing the back bridge at armature 121.

In the trunk holding circuit TC—2 Fig. 3, line relay 212 pulls up again responsive to the closure of the back bridge circuit in the repeater R—1 and at armature 223 again closes the circuit of the release relay 213. The circuits now remain in this condition until the operator responds.

The operator in the tandem manual exchange responds to the lighting of the lamp 307 by operating the push button P of the cord circuit CC—1. The push button P closes a circuit for relay 301, whereupon relay 301 energizes and places ground on the locking conductor 355 at armature 309; connects the winding of relay 304 to the common conductor 357 at armature 310; and at armatures 308 and 311 disconnects conductors 241 and 242 from the corresponding conductors of the cord circuit and connects them instead to conductors 356 and 358 of the call indicator. The operator holds the push button P operated until the number comes in on the call indicator.

Responsive to the shifting of the conductors 241 and 242, line relay 302 of the cord circuit falls back and puts out the lamp 307. In the trunk circuit TC—2, Fig. 3, relay 217 now falls back responsive to the above shifting of conductors 241 and 242 and opens a point in its own circuit at armature 237. At armature 236, relay 217 connects relay 210 in multiple with relay 216 through the working contact and armature 232. Accordingly, relay 210 energizes and at armature 219 closes a holding circuit for the release relay 213. At armatures 218 and 220, relay 210 disconnects the incoming conductors 207 and 209 from the windings of line relay 212 and connects them directly to the conductors 241 and 242, at the same time disconnecting the con-

ductors 241 and 242 from the back-bridge circuit of the holding circuit. It will be noted that relay 238 of the timer T—2 is connected in multiple with relay 210. The effect of this will be described subsequently.

Responsive to the operation of relay 210, line relay 212 of the trunk circuit TC—2 falls back, but the release relay 213 is maintained operated at armature 219 of relay 210. In the repeater R—1, Fig. 2, back bridge relay 114 falls back responsive to the operation of relay 210, Fig. 3, and closes at armature 133 a circuit through the resting contact and armature 132 for relay 112. Relay 112 energizes and closes a locking circuit for itself at armature 129; opens a point in the circuit of relay 113 at armature 128, and at armature 130 connects relay 107 in multiple with its own winding. Relay 107 energizes and at armatures 115 and 117 disconnects the conductors 104 and 106 from the windings of line relay 109 and connects them to conductors 135 and 136, at the same time disconnecting the latter conductors from the back bridge circuit of the repeater. Line relay 109, now falls back, but release relay 110 is maintained operated at armature 116 of relay 107. The timer relay is connected in multiple with relay 107 with results to be described subsequently.

In the director, relay 907, whose lower winding has been maintained energized in series with line relay 109 of the repeater R—1, now falls back and at armature 932 opens a point in the circuit of its lower winding. At armature 933, relay 907 closes a circuit through armature 930 and its working contact for relay 905. Relay 905 energizes and at armatures 925 and 926 disconnects the impulse conductors 36 and 604 from the winding of relay 907 and connects them to the sending wipers 938 and 940 of the sending switch SS'. At armature 927 relay 905 closes a circuit through the interrupter 931 for the stepping magnet 937 of the sending switch SS'. This circuit includes the resting contact and armature 630 of relay 621 Fig. 7, and the conductor 601. Accordingly, magnet 937 commences to energize and deenergize under the control of the interrupter 931, and the wipers 938—940 are advanced one step upon each deenergization of the magnet 937. This operation continues until the wipers have made one half revolution. The first four sets of bank contacts are assigned to the first code digit; the second four sets of bank contacts are assigned to the second code digit; the third four sets of bank contacts are assigned to the thousands digit etc. In this case, the wipers of the code register CR—1 Fig. 9 have been set on the fifth set of the associated bank contacts, and the wipers of the code register CR—2 have been set on the fourth set of bank contact, as hereinbefore explained.

On the first step of the wipers 938—940,

the negative wiper 940 encounters a grounded contact, and the positive wiper encounters the conductor which is connected through a resistance winding to certain contacts in the lower bank of the code register CR-1. However, since the wipers of the code register are on the fifth set of bank contacts, no circuit is closed over the loop at this time.

On the second step of the wipers of the sending switch, the positive wiper 938 encounters a grounded bank contact and the negative wiper 940 encounters a conductor connected to battery through a resistance, which conductor is also connected to the two lower banks of the code register CR-1 so that the resistance is short circuited in case the code register is standing in the second, third, seventh, or eighth position. Since the code register is standing in its fifth position, the resistance is not short circuited and only the negative receiving relay Fig. 5 is operated, the impulse being what is termed a light negative impulse.

On the next step of the wipers of the sending switch SS', the negative wiper 940 again encounters a grounded bank contact, and the positive wiper 938 encounters the third bank contact which is connected through a resistance winding to the fourth and ninth contacts in the bank of the first code register. No impulse is sent over the loop in this position of the sending switch however, owing to the fact that the wipers of the code register are standing on the fifth set of bank contacts.

Upon the fourth step of the wipers of the sending switch, the positive wiper 938 again encounters a grounded bank contact, and the negative wiper 940 encounters a conductor that is connected to battery through a resistance winding. This conductor also extends to the upper bank of the code register CR-1 and is there connected to the fifth, sixth, seventh, eighth, and ninth bank contacts. That being the case, the resistance in this lead is short circuited, as the upper wiper of the code register is connected to battery and is standing on the fifth associated bank contact. The result is that a heavy negative impulse is sent over the two talking conductors and through the receiving relays 409-411 Fig. 5. The negatively-polarized relay 409 is operated owing to the direction of the current, and the non-polarized marginal relay 410 is operated owing to the relatively high strength of the current.

As the wipers of the sending switch SS' pass through the four positions assigned to the code register CR-2, two light negative impulses are transmitted in a manner similar to that described above, and a positive impulse is transmitted between the two light negative impulses, all positive impulses being light. The two light negative impulses are the usual switching impulses and are sent by the sending switch SS' without any assist-

ance from the register, but the light positive impulse which is sent with the wipers of the sending switch SS' in their seventh position is sent through the conductor that terminates in the fourth contact in the lower bank of the code register CR-2, the impulse being light on account of the resistance in such conductor.

In a similar manner, the further advance of the sending switch SS' results in the transmission of the impulses corresponding to the setting of the thousands, hundreds, tens and units registers.

In the call indicator, Fig. 5, when the light negative impulse of the first digit 5 comes in it operates the negative relay 409, which relay at armature 402 closes a circuit through armature 404 and its resting contact for relay 402 in series with the lower winding of the marginally adjusted relay 401. Relay 402 operates, but relay 401 does not operate owing to its marginal adjustment. At armature 407, relay 402 closes a locking circuit for itself that includes the upper winding of relay 401. No current flows over this locking circuit through the upper winding of relay 401 at this time, however, on account of the fact that the upper winding is grounded now at both terminals. At armature 406, relay 402 closes a circuit through the upper armature and resting contact of the upper switching relay of the code register C-1 for the lower switching relay. The said lower switching relay operates and at its lower armature switches the circuit controlled thereby from the associated "A" relay to the corresponding relay in the next storage set. At its upper armature, the said lower switching relay closes a locking circuit for itself including the associated upper switching relay. The upper switching relay does not operate at this time, owing to the fact that it is grounded at both terminals.

When the light negative impulse subsides, relay 409 falls back and at armature 412 opens the initial circuit of relay 402, whereupon the locking circuit of relay 402 through the upper winding of relay 401 becomes effective. Relay 402 remains energized over this locking circuit and relay 401 operates owing to the fact that current is now flowing through both its windings. At armature 404, relay 401 switches armature 412 of relay 409 to the junction of its lower winding and the winding of relay 402; at armature 403 it places a shunt around armature 406 and its working contact; and at armature 405 it shifts armature 413 of relay 410 from the "B" operating conductor to the "D" operating conductor.

When the heavy negative impulse of the first code digit comes in, the negative relay 409 operates again, and the marginal relay 410 is operated. At armature 412 relay 409 closes a circuit for the lower winding of relay 401 independent of relay 402 and the up-

per winding of the said relay 401. When this occurs, relay 402 restores, and relay 401 remains operated. Marginal relay 410 closes at armature 413 a circuit through armature 405 and its working contact and the inner lower armature and resting contact of the upper switching relay of the code register C—1 for the right hand winding of the "D" storage relay of the code register C—1. This relay operates over this circuit and closes a locking circuit for itself at its inner armature. When the impulse subsides, relays 409 and 410 fall back and relay 409 opens the circuit of the lower winding relay 401, whereupon relay 401 falls back and at armature 403 opens the initial circuit of the lower switching relay of the code register C—1. When this occurs, the shunt is removed from around the upper switching relay and the two switching relays are energized in series. At its upper armature, the upper switching relay extends the switching-relay operating conductor to the corresponding conductor of the code register C—2, and at its two lower armatures it extends the circuits controlled thereby to the corresponding armature of the next switching relay.

In a similar manner, the two light negative impulses in the second code digit 4, operate the negative relay 409 twice, and the resulting operation of the relays 401 and 402 brings about the operation of the two switching relays of the code register C—2. Between the two operations of the negative relay 409, the positive relay 411 is operated once, closing at armature 414 a circuit through armature 408 and its working contact middle armature of the lower switching relay of the code register C—2 and its working contact, corresponding armature and resting contact of the lower switching relay of the thousands register, and the right hand winding of the "C" relay of the second code register C—2. This relay operates over this circuit and closes a locking circuit itself at its inner armature.

In a similar manner the storage relays of the thousands, hundreds, tens and units registers operate to store the remaining digits.

When the upper switching relay of the units register operates at the end of the recording of the units digits, it grounds at its upper armature the lamp lighting lamp conductor 415. It will be noted that the lamps are connected in series in pairs and that current now flows through all the lamps except one lamp in each set which is short circuited. The lamps used in the indicator are such that they do not light to their normal brilliancy except when they have the full battery voltage placed across their terminals. Accordingly, with two lamps in series, they are not lighted to any noticeable extent. In each set of lamps, the mate of the short circuited lamp is lighted to its full brilliancy, displaying the number to the operator. For ex-

ample, in the code register C—1, the "D" relay is operated and the A B C relays are not operated. Accordingly, battery is supplied to the junction of the "0" and 5 lamps, short circuiting the 0 lamp and permitting the 5 lamp to light; in the code register C—2, the "C" relay is operated and the A, B, and D relays are not operated. Accordingly, ground potential is placed on the junction of the fourth and ninth lamps, short circuiting the ninth associated lamp, permitting the fourth lamp to light. Similarly a single lamp is lighted in each of the other sets, the particular lamp which is lighted being dependent on the setting of the storage relays.

When the operator has noted the displayed number, she releases the push button P and proceeds to complete the connection in a manner to be pointed out subsequently. When the push button P is released, relay 301 falls back, and at armatures 308 and 311 connects conductors 241 and 242 back to the windings of line relay 302 again, and at armature 309 removes ground from conductor 355 whereupon the locked-up relays of the call indicator fall back and the lighted lamps become extinguished.

In the combination director, wiper 939 closes, in its twenty-fourth position, a circuit through the next to the last bank contact, armature 936 and its working contact, and conductor 607, for the upper winding of the combination two-step switching relay 621, Fig. 7. Relay 621 operates through its first step only when the upper winding alone is energized, as the upper winding comprises a relatively small number of turns of wire having a relatively high resistance per turn. At its first step armature 629, relay 621 closes a locking circuit for itself through its lower winding. This lower winding is short circuited at this time however, by the ground supplied to the junction to the two windings over conductor 607. Upon the next step of the wipers of the sending switch SS', Fig. 10, ground is removed from conductor 607, whereupon the locking circuit through the lower winding of relay 621 becomes effective and the relay operates fully. At armature 627, relay 621 closes the above-described circuit for switching relay 12, Fig. 1, and at armature 630 it opens the impulsing circuit including the interrupter 931, Fig. 10, and stepping magnet 937. This opening of the interrupter circuit occurs with the wipers of the sending switch SS' in their normal position, and the wipers of the sending switch are prevented from advancing further, as they would have to be rotated another half revolution if they are permitted to advance beyond their normal position at this time.

When the circuit of the switching relay 12, Fig. 1, is closed by the switching relay 621, Fig. 7, relay 12 operates and connects up the

back bridge circuit of the trunk circuit TC-1 at armatures 20 and 24, freeing the director by opening the circuit of relay 26 at armature 22.

- 5 In the director, relay 622, upon falling back when the director is freed, closes the usual restoring circuits at armatures 631, 633, and 634, and at armature 632 removes ground from conductor 608, whereupon relay 621, Fig. 7, and relays 901, 903, 904, 905, 906, and 908 closes a normal restoring circuit for the sending switch SS', which is used in case the director is freed while the sending switch SS' is off-normal.

- 15 Considering now the operation of the timers T-1, Fig. 2, and T-2, Fig. 3, it will be noted that the starting relay 151 of the timer T-1 is in multiple with the switch-through relay 107 of the repeater R-1, and 20 that the starting relay 238 of the timer T-2 is in multiple with the switch-through relay 210 of the trunk circuit TC-2. Considering first the operation of the timer T-2, relay 238, being slightly slow to pull up, operates shortly after the operation of the switch-through relay 210 occurs and closes at its lower armature a circuit for relay 240. Relay 240 operates and opens at its upper armature a point in the circuit of relay 215.

- 30 At its upper armature, relay 238 closes a circuit for the slow to pull up relay 239. After a slight interval, relay 239 operates and opens the circuit of the slow acting relay 240 and closes a further point in the circuit 35 of relay 215. At the end of a further interval, the slow acting relay 240 falls back and completes the circuit of relay 215. At armature 228, relay 215 places a second ground on the release trunk conductor 208 so as to maintain 40 this conductor grounded independent of the release relay 213; prepares the regular back bridge circuit at armature 230; at armature 229 opens the circuit of relays 216, 210, and 238, and closes a locking circuit for itself; 45 and at armature 231 opens a point in the circuit of the lower winding of relay 217 so as to prevent this relay from operating after relay 216 falls back. Responsive to the opening of their circuits, relays 216, 210, and 238 fall back, and relay 238 opens the initial energizing circuit of relay 215, leaving relay 215 energized over its locking circuit through armature 226 and its working contact and armature 229 and its working contact. Relay 50 238 also opens the circuit of relay 239, and relay 239 falls back.

- Relay 210, upon falling back, shifts the conductors 207 and 209 back to the windings of line relay 212 again, and it connects the conductors 241 and 242 back to the back bridge circuit of the trunk circuit TC-2. The time required for the above operation to take place is long enough to permit the call indicator impulses to pass through before relay 210 65 falls back.

It will be noted that relay 217 is now de-energized and that there is no bridge across the conductors 241 and 242 until line relay 212 pulls up. Line relay 212 cannot pull up again until the timer T-1, Fig. 2, has completed its operation. Theoretically, perhaps, the timer T-1 should complete its operation at the same time that the timer T-2 completes its operation. In practice, however, the two timers cannot be depended upon to operate in exact synchronism, and arrangements are provided to take care of this contingency. It will be noted that the circuit of release relay 213 is opened at armature 219 when relay 210 falls back. Relay 213 however, is the usual slow acting release relay and it remains operated for an interval in order to give the preceding timer a chance to finish its operation if it has not already done so. A further interval of time may be utilized in case the relay 213 gets back before the preceding timer has finished. This is the interval required for relay 215 to fall back after its circuit is opened by the release relay 213, as relay 215 maintains the release trunk conductor 208 grounded at armature 228.

In the timer T-1, the relays 151, 152, and 153 operate in a manner similar to that described in connection with the timer T-2 to close a circuit for relay 111. When this circuit is closed, relay 111 operates and at armature 126 grounds conductor 105 at a second point, and at armature 127 closes a locking circuit for itself including armature 125 and its working contact, and at the same time opening the circuit of relays 112, 107 and 151. Relay 151 falls back and opens at its lower armature the initial circuit of relay 111, leaving relay 111 energized over its locking circuit which includes armature 127 and its working contact. Relay 107 falls back when its circuit is opened and opens the circuit of the release relay 110 at armature 116, and at armatures 115 and 117 shifts conductors 104 and 106 back to the windings of line relay 109 again, at the same time connecting conductors 135 and 136 to the back bridge circuit of the repeater. It will be noted that the repeater R-1, like the trunk circuit TC-2, is able to maintain the associated release trunk conductor grounded for an interval after relay 107 falls back, independent of the operation of the line relay 109. This is the interval required for relays 110 and 111 to fall back one after the other. This interval is not needed particularly in this case, as there is no preceding repeater in the connection, but it may be used in case the repeater R-1 is taken into use to complete a connection that includes a preceding repeater.

Responsive to the line relay 119 being connected up to conductors 104 and 106 again by relay 107, line relay 109 energizes in series with the back bridge circuit of the trunk cir-

cuit TC—1, Fig. 1, the bridge across the conductors 5' and 7' including the working contacts and armatures 20 and 24, the impedance 9, upper armature and working contact of line relay 10, and the right hand winding of the electropolarized relay 8. Upon energizing, relay 109 closes at armature 120 the circuit of release relay 110, and at armature 121 again closes the circuit across conductors 135 and 136 for line relay 212 of the trunk circuit TC—2, Fig. 3. Line relay 212 energizes when this circuit is closed and at armature 223 again closes the circuit of release relay 213. If relay 213 has not fallen back, it remains operated, but if it has already fallen back it operates again and at armature 226 again closes the locking circuit through armature 229 and its working contact for relay 215. It is assumed that in no case will the difference in the operation times of the timers be enough to permit relay 215 to fall back. At armature 224, line relay 212 completes a circuit across conductors 241 and 242 which includes the normally closed contacts controlled by armatures 218 and 220, left hand winding of the polarized relay 211, armature 224 and its working contact, impedance 214, and the working contact and armature 230. When this circuit is closed, line relay 302 of the cord circuit CC—1, Fig. 4, operates and again lights the lamp 307 at armature 312, provided the operator has not yet inserted the plug of the cord circuit into a jack to complete the connection.

Considering now the operations performed by the tandem operator, upon releasing the push button P, the operator depresses the push button P' so as to connect the talking conductors of her head set with the order wire leading to the called manual office. The operator now communicates with the operator at the switchboard in the terminating manual office over the order wire OW, and the second operator assigns an idle trunk line, for example, the trunk line extending from the jack J' to the cord circuit CC—2. The tandem operator now releases the push button P' and inserts the plug of the cord circuit CC—1 into the jack J'. When this occurs, relays 305 and 306 operate in series with the sleeve resistance 324, and close points in the talking circuit at armatures 318, 320, 321, and 323. Relay 306 at armature 322 opens the circuit of the lamp 307 in case it has been closed again at armature 312 by the reoperation of line relay 302. The high resistance relay 343 in the cord circuit CC—2 now energizes in series with the battery feed relay 303 of the cord circuit CC—1, but relay 303 does not operate at this time owing to the high resistance of relay 343. At armature 348, relay 343 prepares the ringing circuit.

Upon learning the number of the desired line, the terminating manual operator tests the line by tapping the tip of the plug of the

cord circuit CC—2 against the sleeve of the jack in the usual manner. Assuming that the test indicates that the line is idle, the operator inserts the plug into the jack, whereupon sleeve relay 345 operates in series with the cut-off relay 354. Relay 354 operates to clear the called line of its attachments, and relay 345 closes at armatures 351 and 353 points in the talking circuit, at the same time disconnecting the tertiary winding of the operator's induction coil from the tip of the plug. The ringing circuit is now completed from the common ringing lead through the working contact and armature 348, the resting contact and armature 350, and the working contact and armature 353 for ringing the bridged bell at the called substation, the ringing current returning to battery through armature 351 and its working contact, armature 349 and its resting contact, and the upper winding of the ring-cut-off relay 344. Relay 344 is not operated at this time on account of the fact that there is a condenser in the ringing circuit at the called substation.

When the called subscriber responds to the ringing of his bell by removing his receiver, the transmitter bridge is substituted for the ringer bridge, whereupon relay 344 operates and at its middle armature removes the shunt from around its lower winding, so that the relay will now remain operated in series with sleeve relay 345 independent of its upper armature. At armatures 349 and 350, relay 344 opens the ringing circuit and completes the talking circuit. Battery-feed relay 342 now energizes over the called line and at armature 346 short circuits the lower winding of the high resistance relay 343, whereupon the back bridge relay 303 in the cord circuit TC—1 operates and at armatures 314 and 315 reverses the connection between the windings of line relay 302 and conductors 241 and 242. When this occurs, the direction of current flow is reversed in the said conductors 241 and 242, and the electro-polarized relay 211 in the trunk circuit TC—2, Fig. 3, operates and makes a similar reversal as regards conductors 207 and 209 and line relay 212. Electro-polarized relay 109 of the repeater R—1, Fig. 2, now responds and relays the reversal back to the electropolarized relay 8 in the trunk circuit TC—1, Fig. 1, which latter relay operates and reverses the direction of the current flow in the calling line.

The two subscribers may now converse with each other in the usual manner, and when the conversation is over they are both expected to replace their receivers.

When the receiver is replaced at the called substation, battery-feed relay 342 of the cord circuit CC—2 falls back and again includes the lower winding of relay 343 in the circuit of battery-feed back-bridge relay 303 of the cord circuit CC—1. Relay 303 now falls back and reverses the current flow in conduc-

tors 241 and 242 to normal, whereupon the electropolarized relays 211, Fig. 3, 109, Fig. 2, and 8, Fig. 1, fall back. When the receiver is replaced at the calling substation, line relay 10 of the trunk circuit TC-1, Fig. 1, falls back and opens the circuit of the slow acting relay 11 at armature 15, and at its upper armature opens the circuit of the line relay 109 of the repeater R-1, Fig. 2. Relay 109 falls back and opens the circuit of the associated release relay 110 at armature 120, and at armature 121 opens the circuit of line relay 212, Fig. 3. Line relay 212 falls back and opens at armature 223 the circuit of the associated release relay 213, and at armature 224 opens the circuit of line relay 302 of the cord circuit CC-1, line relay 302 falls back and at armature 312 closes a circuit for the combined answering and disconnect lamp 307. The lamp 307 now becomes lighted, and the operator pulls down the connection. Relay 343 of the cord circuit CC-2 now falls back and at armature 347 closes a circuit through the working contact and armature 352 for lamp 341. The terminating manual operator now removes the plug of the cord circuit from the jack of the called line. Responsive to the falling back of the various release relays mentioned above, the connections set up through the automatic switches is released in the usual manner.

Call to tandem manual office

It will now be assumed that the director selector DS, Fig. 1, takes the director shown in Figs. 6-10 into use responsive to the call intended for the subscriber at substation 355, Fig. 4, whose line terminates at the tandem manual office. The director is prepared for operation in the usual manner, and the office register OR and the thousands, hundreds, tens, and units registers are set in the manner hereinbefore described when the number is dialled.

It has been assumed that the bank contacts 724 Fig. 8 in the bank of the office register OR are the ones assigned to the tandem manual office. Accordingly, the first three of the contacts 724 are cross connected to the first, third, and eighth impulse stop conductors respectively, so as to cause the sender to transmit the office code digits one, three, and eight so that the call will be trunked to the tandem manual office. In order to bring about the operation of the tandem-manual-office relay 901, Fig. 10, the fourth bank contact of the set is cross connected to the conductor 701 leading to the said relay 901. It has been assumed that the setting up of the code "OO" on the first two registers of the call indicator, Fig. 5, indicates that the call is for a line in the tandem manual office. Accordingly, the last two bank contacts in the contact set 724 are cross connected on the I. D. F. to the tenth impulse stop con-

ductor so as to cause the two code registers CR-1 and CR-2, Fig. 9, to be set in their tenth positions in order that the code portion of the call indicator will be properly adjusted when the call indicator impulses are transmitted.

That being the case, relay 901 is again operated over conductor 701 when the sequence switch S' arrives in its fourth position after the transmission of the third of the office code digits one, three, and eight. Relay 901 operates in the manner hereinbefore described to prevent the further impulses generated by the regular sender SS, Fig. 7, from going out over the loop circuit and it prepares at armature 909 an impulse circuit over armatures 637, 640, and 645, Fig. 7, for the code register CR-1 and CR-2. Relay 901 at armature 913 extends the ground potential to conductor 702, with the result that the sequence switch S' is caused to advance through the fourth-code digit position in the manner hereinbefore described. The regular sender SS now transmits the two code digits 0 and 0 over the impulse conductor 610 and sets each of the code registers CR-1 and CR-2 in its tenth position. After this has been accomplished, the further operation of the sending switch SS is prevented in the manner hereinbefore described, and, as soon as the units register, Fig. 9, has gone off-normal, if it has not already done so, a circuit is completed at the off-normal contacts of the units register over conductor 504, through the lower armature and resting contact of relay 521, Fig. 6, conductor 510, lower contacts of the relays 624 and 625, conductor 609, lower off-normal contacts of the code register CR-2, and armature 911 and its working contact, for relay 903. Relay 903 pulls up and opens the loop across the outgoing impulse conductors at armature 919, and this loop is again closed in the manner hereinbefore described responsive to the operation of relay 904, whose circuit is closed at armature 920.

When the sending switch SS' operates a half revolution responsive to the connecting up of the call indicator, Fig. 5, (it being assumed that the connection is trunked to the tandem manual office through the switches shown in Figs. 2 and 3), the sending switch SS' sends two light negative impulses as it passes through its first four positions and it transmits two light negative impulses again as it passes through its second four positions. This is on account of the fact that all the wipers of the code registers CR-1 and CR-2 Fig. 9, are standing on dead contacts when they are in their tenth position, the sending switch SS' being connected up so as to send two light negative impulses in this case. The impulses sent in the remaining positions of the sending switch SS' depend, as usual, up-

on the setting of the thousand, hundred, ten, and units registers.

After having sent the call indicator impulses, the director is freed responsive to the hereinbefore-described switch-through operation.

In the tandem manual office, Fig. 4, the two light negative impulses of the first code digit operate the negative relay 409 twice, but the marginal relay 410 is not operated, nor is the positive relay 411 operated. The result is that the controlling relays 401 and 402 operate in the manner hereinbefore described to operate the upper and lower switching relays of the code register CR-1. The four storage relays of the register C-1 remain nonoperated. In a similar manner, the upper and lower switching relays of the code register C-2 are operated under the control of the negative relay 409 when the second digit 0 is received, and the storage relays of this register remain nonoperated. The setting of the storage relays of the thousands, hundreds, tens, and units registers is dependent upon the number of impulses received from the director.

When the lamp lighting conductor 415 is grounded upon the operation of the upper switching relay of the units register, the O lamps in the code registers C-1 and C-2 are lighted, as none of the associated storage relays are operated. Also, the appropriate lamps in the thousands, hundreds, tens, and units registers are lighted to display the number of the called line. It will be recalled that in the previous connection the ring-cut-off relay 305 energized immediately upon the insertion of the plug of the cord circuit CC-1 in jack J', and that no ringing current was sent out by the cord circuit CC' for that reason. In the present case, however, the ringing current must be transmitted from the cord circuit CC' and arrangements must be provided to delay the operation of the ring-cut-off relay until the called subscriber has answered. It has been assumed that there is no terminating manual office reached through the tandem manual office whose code number begins with the digit 0. Accordingly, any time the O lamp of the register C-1, Fig. 5, operates, the call is intended for the tandem office. This fact has been made use of by the arrangement involving the relay 304 of the cord circuit CC-1. This relay is connected in multiple with the O lamp of the register C-1 through conductor 357 and armature 310 and its working contact when the switching relay 301 of the cord circuit is operated. Relay 304 is adjusted so that it will not operate in multiple with the O lamp unless the 5 lamp is short circuited, as in the present case. The resistance connected around the 5 lamp is for the purpose of restoring the balance between the two lamps when relay 304 is con-

nected in multiple with the O lamp. Upon operating in multiple with the O lamp, relay 304 locks itself in a local circuit at armature 317, and at armature 316 short circuits the lower winding of relay 305 through the resting contact and armature 319.

Upon noting the number displayed on the call indicator, and upon noting that the office set-up indicates that the line is a local line, the operator releases the push-button P 75 whereupon relay 301 falls back and the operated relays of the call indicator restore. Relay 304 is maintained operated through armature 317 and its working contact. The operator now inserts the plug of the cord circuit CC-1 into the jack J, assuming that the usual busy test indicates that the line is idle. Relay 306 pulls up in series with the cut-off relay 325 of the called line, but relay 305 does not operate at this time owing to the fact that it is short circuited at armature 316 of relay 304. It will be noted that relay 304 is short circuited at armature 313' of sleeve relay 306 when the latter pulls up if the line relay 302 has not again reoperated responsive to the usual hereinbefore-described termination of the cut-through condition at the repeater R-1, Fig. 2, and at the trunk circuit TC-2, Fig. 3. It may be assumed that in most cases the line relay has again operated by the time the operator has made the busy test and placed the plug in the jack, but, if it has not, the slow-acting relay 304 is able to remain operated until the line relay 302 operates again, as, in addition to the usual slow effect caused by the copper slug, the relay is slow due to the fact that it is short circuited. With the line relay 302 operated, and with the sleeve relay 306 operated, the answering and disconnect lamp 100 307 is extinguished. Ringing current is now projected out over the called line from the common ringing lead and through the resting contact and armature 320, and armature 323 and its working contact, the return path to ground being through the tip of the cord circuit, armature 321 and its working contact, armature 318 and its resting contact, upper winding of relay 305, and the exchange battery.

When the called subscriber responds by removing his receiver, the ring-cut-off relay 305 operates, and at armature 319 removes the shunt from around its lower winding so as to permit the relay to remain operated in series 120 with relay 306 and independent of its upper winding. At armatures 318 and 320, relay 305 opens the ringing circuit and completes the talking circuit. The battery feed relay 303 now operates over the called line and reverses the connection to the conductors 241 and 242, with the hereinbefore-described results. The connection is released in the usual manner when the calling subscriber hangs up his receiver, and relay 302 of the cord circuit 125 130

cuit CC—1 pulls back and prepares a disconnect circuit for the lamp 307 at armature 312. At armature 313, relay 302 places a shunt around relay 304 through armature 313' and its working contact. Relay 304 falls back after a slight interval and opens its locking circuit at armature 317. At its upper armature, relay 304 completes the disconnect circuit for the lamp 304, and the operator pulls 10 down the connection.

Call to terminating manual office

Referring now particularly to Fig. 3, it is assumed that the trunk circuit TC—3 and the timer T—3 are similar to the trunk circuit TC—2 and the timer T—2. It is assumed that the outgoing conductors extending to the right from the trunk circuit TC—3 extend to a terminating (non-tandem) manual office. 20 When this office is called, it is necessary to send only four digits to the call indicator therein, as there is only one possible office destination.

It is assumed that the set of bank contacts numbered 722 in the bank of the office register OR, Fig. 8, are assigned to the terminating manual office reached through the trunk circuit TC—3, Fig. 3. Assuming that the line switch of a calling subscriber, who desires to 25 converse with a subscriber of such terminating office, seizes the trunk line extending through the trunk circuit TC—1, Fig. 1, to the selector S—1, and that the director selector DS seizes the director shown in the drawings, the dialling of the office and subscriber digits of the number results in the setting of the office register OR, Fig. 8, on the bank contacts 722 and in the setting of the thousands, hundreds, tens, and units registers, Fig. 9, in 30 accordance with the four subscriber digits in the number. As the trunks to the office in question come from the tenth level of the selector S—3 Fig. 3, the first three bank contacts in the set 722 are cross connected to the first, 35 third, and tenth impulse stop conductors. Accordingly, the director transmits the code digits 1, 3, and 0 when the sending operation is started at the end of the setting of the office register OR. It will be assumed that 40 the call is trunked through the switches shown in Figs. 2 and 3 and that the trunk circuit TC—3 Fig. 3, is once seized by the selector S—3.

In order to secure the operation of the terminating-manual-office relay 902, Fig. 10, the 45 fourth contact in the set 722, Fig. 8, is cross connected at the I. D. F. to conductor 703 leading to relay 902, Fig. 10. Accordingly, when the fourth wiper of the office register OR is 50 grounded when the sequence S' arrives in its fourth position after the three office code digits have been sent, a ground potential is extended through the fourth wiper of the office register and the fourth bank contact in 55 the set 722 to the relay 902, over conductor 703,

and through the normally closed contacts controlled by armature 916 of the relay 902. Relay 902 operates and closes at armature 716 a locking circuit for itself, at the same time opening its initial circuit. At armature 915, 70 relay 902 prepares a circuit for relay 903; it opens at armature 914 a point in the previously traced circuit including conductor 811 and the off-normal contacts of the hundreds register for operating the sending switch SS after the code digit positions have been passed by the sequence switch S', and at armature 917, it connects the grounded conductor 703 to the conductor 704 leading back to the I. D. F. Conductor 704 is cross-connected on the I. D. F. to the skip conductor 501, causing the advance of the sequence switch S' to the fourth position. As the fifth and sixth bank contacts are connected on the I. D. F. to the skip conductor, the skipping operation continues until the wipers of the sequence switch S' have advanced through the fifth and sixth positions. The sequence switch S' remains 80 in its seventh position until the director is released. Since it is unnecessary to send any office-code digits to the call indicator in the present case, arrangements are provided for causing the call-indicator sender SS' to skip its code-digit positions without transmitting any call indicator impulses. This skipping 85 operation is brought about at armature 918 of relay 902, where the magnet 937 is connected through its local interrupter contacts to the normal position contact in the bank of wiper 939 and to the first seven contacts in 90 such bank, the connection to the normal contact including armature 923 and its resting contact. Accordingly, the magnet 937 operates in a buzzer-like manner and advances the wipers 938—940 step-by-step until they arrive 95 in their eighth position. At armature 941, relay 902 removes battery from the resistance associated with the eighth contact in the bank of wiper 940, so as to prevent a preliminary negative impulse from being set when the 100 wipers are connected up subsequently at relay 905.

When the units register, Fig. 9, has been set, or when the terminating manual office relay 902 has operated, whichever is completed last, a circuit is closed for relay 903 as follows: from ground through the off-normal contacts of the units register, Fig. 9, conductor 504, armature and resting contact of relay 521, Fig. 6, conductor 510, conductor 605, working contact and armature 915, and relay 903 to battery. When relay 903 operates over this circuit, it opens the outgoing loop at armature 919 and at armature 920 closes a circuit for relay 904 with the result that relay 115 904 operates after an interval and again closes the bridge across the impulse conductors by operating relay 907 in the manner hereinbefore described. Relay 907 operates relay 906 at armature 933. 120 125 130

It will be understood that the momentary opening produced in the outgoing control circuit by the joint action of relays 903, 904, and 907 is relayed by the repeater R-1, Fig. 1, to the trunk circuit TC-3, Fig. 3, and results in the 5 operation of the trunk circuit TC-3 in a manner similar to that explained in connection with trunk circuit TC-2 to signal the operator by closing a bridge across the associated outgoing trunk conductors.

When the operator in the terminating manual office responds by connecting the conductors of the trunk line incoming to her position to her call indicator, the talking conductors 10 are switched through in the hereinbefore-described manner at the repeater R-1 and at the trunk circuit, TC-3, and relay 907, Fig. 10, falls back and operates relay 905 at armature 933, connecting the impulse conductors 15 to the wipers 938 and 940 of the sending switch SS'. At the same time, the operation of the sending switch SS' is started at armature 927. Upon rotating around the remaining portion of the half revolution, the 20 wipers 938 and 940 transmit impulses corresponding to the digits registered on the thousands, hundreds, tens, and units registers 25 Fig. 9.

The call indicator in the instant called 30 office may be the same as the one shown in Fig. 5, except that the code registers C-1 and C-2 are omitted, and the contacts of the relays 401 and 402 are suitably connected to the contacts of the switching relays of the remaining 35 registers. The cord circuit used may be like the cord circuit CC' except that relay 304 and the associated connections are omitted, and battery is connected directly to the contact corresponding to the resting contact 40 of armature 319.

Returning now to the director, the switching relay 621 goes through its previously-described two-step operation as the wipers of the sending switch SS', Fig. 10, arrive in the 45 twenty-fourth position and advance to the twenty-fifth position. It will be noted that the circuit initially established for driving the wipers of the sending switch SS' automatically out of their normal position responsive 50 to the operation of relay 902 is now open at armature 923 of relay 904. When relay 621 operates fully, the connection is switched through at the trunk circuit TC-1 and the director is freed.

The switched-through condition at the repeater R-1 and at the trunk circuit TC-3, Figs. 2 and 3, is terminated in the usual manner and the conversation may proceed as soon as the operator in the called manual office 60 has completed the connection and secured a response from the called subscriber.

When the conversation is completed the connection is broken down in the usual manner.

Non-tandem automatic-to-manual call

It is assumed that there is a manual office reached directly from the originating automatic office from the second level of the selector S-1 Fig. 1. As the selector S-1 is held up from the trunk circuit TC-1, the talking conductors could extend directly to the manual office from the bank contacts of the selector S-1 if it were not for the fact that the manual operator must not be signalled until the director is ready to transmit the number, that is, she must not be signalled until all the registers involved have been set, as has been explained hereinbefore. Accordingly, the relay 84 has been provided in connection with the trunk line comprising conductors 88 and 89. This relay is connected between the outgoing trunk line and the bank-contact conductors 81-83.

Assuming that the director is handling a call for a manual office reached through the trunk line comprising conductors 88 and 89, and that the selector S-1, upon being operated in accordance with the digit 2, seizes this trunk line through the conductors 81-83, ground through the test wiper 73 is placed on conductor 82 to make the trunk line busy in the usual manner, and a circuit is closed over conductors 81 and 83 for the lower winding of the two step relay 84, conductor 83 being grounded through the resting contact and armature 87, and the upper terminal of the lower winding of relay 84 being connected through the resting contact and armature 85 to conductor 81. Relay 84 energizes through its first step only, when the circuit is closed through its lower winding, and operates only the first step armature 86. Armature 86 closes a locking circuit for the relay including the upper winding, which however, is practically short circuited by the ground potential applied to the junction of the two windings of the relay over conductors 83 and 81 in series and in series with the outgoing control conductors 35 and 36 of the director.

Now, when the outgoing control circuit is interrupted momentarily by the joint action of relays 903 and 904, Fig. 10, the short circuit is momentarily removed from around the upper winding of relay 84, Fig. 1, and relay 84 operates through its second step. At armatures 85 and 87 the conductors 81 and 83 are disconnected from relay 84 and from ground and are extended to the corresponding conductors 88 and 89, signalling the manual operator as soon as the interruption in the outgoing control conductors of the director is terminated. The remaining part of the call is taken care of in the hereinbefore described manner. It will be understood of course that the manual office reached over conductors 88 and 89 may be a terminating manual office of a tandem manual office.

Operation of the modified director

Referring now to Figs. 11-13, the modification disclosed in these drawings will now be explained. This modification has to do for the most part with an alternative method of terminating the switched through condition at the end of the transmission of the call indicator impulses. Fig. 11 shows also a trunk circuit TC-3 which is a modification of the trunk circuit TC-1 Fig. 1. The modification of the trunk circuit TC-3 consists merely in the elimination of the relay 8 and impedance 9 and in the connection of the conductors of line relay 10 to the back contacts of armatures 20 and 24. The trunk circuit TC-3 is accordingly simpler than the trunk circuit TC-1, but a repeater must be used on each outgoing trunk extending to an automatic office, and a trunk holding circuit must be used on each trunk line outgoing to a manual office. In some cases, the arrangements shown in Fig. 1 prove to be the most economical, while in other cases the arrangement shown in Fig. 11 may be the most economical.

Assuming now that the trunk line leading to the trunk circuit TC-3 is taken into use by a calling line switch, the line release and release relays 1010 and 1011 energize in the usual manner, and relay 1011, at its lower armatures, closes the usual circuits to cause the director selector DS' to select and seize an idle director. Assuming that the director reached through conductors 35-38 is the first one found to be idle, switching relay 1026 energizes and seizes this director when the wipers of the director selector DS' arrive on the associated bank contacts. It is assumed that the director indicated in Fig. 11 is the same director as the one shown in Figs. 6-10 and that relay 1024 and the associated connections have merely been added, leaving the other connections exactly as shown in Figs. 6-10.

Assuming that the call is for a manual-office subscriber, the tandem-manual-office relay 901 or the terminating-manual-office relay 902, depending upon the routing of the call, pulls up and a circuit is closed through the resting contact and added armature 1032 of the switching relay 621 for the added relay 1024. Relay 1024 operates and at armature 1027 removes ground from the working contact of armature 627 so as to delay the switch-through operation slightly, following the operation of relay 621. At armatures 1028 and 1029, relay 1024 prepares a circuit for placing current from the four-hundred-cycle source on the conductors 35 and 36. The director operates in the usual manner when the operator responds to transmit the call indicator impulses, the repeater R-2 Fig. 12 and the trunk circuit TC-4 Fig. 13 being cleared out in a manner to be explained hereinafter.

When relay 621 pulls up to bring about the operation of the switching relay 1012 after all the call indicator impulses have been sent, it prepares the circuit of relay 1012 at armature 627, and at armatures 1030 and 1031 completes the circuit for placing the four-hundred-cycle current on conductors 35 and 36. Relay 621 at armature 1032 opens the circuit of the slow acting relay 1024, and relay 1024 falls back after an interval and opens the connections to the four-hundred-cycle generator at armatures 1028 and 1029, completing the switch through circuit at armature 1027. The director is freed in the usual manner when relay 1012 pulls up.

Assuming now that the repeater R-2 Fig. 12, is involved in a connection set up to a manual office by the modified director shown in Fig. 11, and that the trunk circuit TC-4 is likewise included in the connection further along than the repeater and at the trunk line comprising the conductors 1034 and 1035 outgoing to the manual office. When the repeater R-2 is seized, line relay 1106 operates over conductors 1097 and 1099 and through armatures 1110 and 1113 and their resting contact, and the normally-closed contacts controlled by armatures 1119 and 1120. At armature 1121, relay 1106 closes a circuit for release relay 1107 and prepares at armature 1122 a bridge across conductors 1130 and 1131. Release relay 1107 operates and prepares at armature 1126 a circuit for relay 1108; places ground on the local locking conductor 1132 at armature 1125; at armature 1124, it places ground on the release trunk conductor 1098 so as to hold up the preceding selector; and at armature 1123 completes a bridge across conductors 1130 and 1131 as follows: from conductor 1130 through the normally closed contacts controlled by armature 1110, working contact and armature 1123, armature 1127 and its resting contact, right hand winding of the electro-polarized relay 1105, relay 1109, armature 1122 and its working contact, and the normally closed contacts controlled by armature 1113, to conductor 1131. Responsive to the closure of this bridge, the selector on the distant end of the outgoing trunk line is prepared for operation in the usual manner. It will be noted that when ground is placed on conductor 1132 a circuit is closed through armature 1138 and its resting contact and the resting contact and armature 1129 for relay 1104. Relay 1104, being slightly slow to operate on account of having a stiff adjustment, does not operate at this time owing to the fact that its circuit is opened at armature 1129 by relay 1109 which operates in the bridge established across conductors 1130 and 1131. Current is now flowing through the two windings of the electro-polarized relay 1104, but this relay does not operate at this time owing to the fact that the current is flowing in the right hand winding in the direction opposite

to that in which it must flow in order for the relay to be operated.

When the next digit is dialled, line relay 1106 falls back each time an interruption is produced in its circuit, and at armature 1122 it momentarily opens the bridge across conductors 1130 and 1131 each time it falls back. This results in the usual operation of the selector on the distant end of the outgoing trunk line. Each time it falls back, relay 1106 at armature 1121 closes a circuit through armature 1117 and its resting contact, and armature 1126 and its working contact, for relay 1108. Relay 1108 operates the first time its circuit is closed, and, being slow acting, remains operated during the entire digit. At armature 1128, relay 1108 opens a point in the circuit of relay 1104 so as to prevent this relay from operating due to the fact that relay 1109 falls back while the digit is being dialled. At armature 1127, relay 1108 makes the usual circuit change so that the impulses are repeated over a circuit path independent of relay 1109 and the right hand winding of relay 1105.

At the end of the digit, relay 1108 falls back and relay 1109 again pulls up.

When the trunk circuit TC-4, Fig. 13, is seized over conductors 1197-1199, line relay 1206 operates over conductors 1197 and 1199 and closes at armature 1224 a circuit for release relay 1207. Relay 1207 operates and prepares at armature 1227 a circuit for the lower winding of relay 1210; grounds the local locking conductor 1236 at armature 1226; and at armature 1225 places ground on release trunk conductor 1198 so as to maintain the preceding selector operated.

As the operator must not be signalled by the closure of the bridge across the outgoing conductors 1234 and 1235 until the director momentarily opens the outgoing control circuit, the circuits remain in this condition until such interruption is produced, whereupon the interruption is repeated by the repeater R-2, Fig. 12, and line relay 1206 in the trunk circuit TC-4 falls back momentarily. At armature 1224, a circuit is closed through armature 1127 and its working contact and armature 1230 and its resting contact for the lower winding of relay 1210. Relay 1210 operates and at armature 1233 closes a bridge across the conductors 1234 and 1235 through its upper winding. The distant line relay in the operator's cord circuit operates over this bridge and the relay 1210 is maintained operated through its upper winding independent of its lower winding. At armature 1232, relay 1210 closes a circuit for relay 1209, whereupon relay 1209 operates and prepares at armature 1228 a circuit for relay 1204, and opens the armature 1230 the circuit of the lower winding of relay 1210, leaving relay 1210 operated through its upper winding.

When the operator responds by connecting her call indicator to the trunk line, the cur-

rent flow over conductors 1234 and 1235 ceases and relay 1210 falls back and completes at armature 1232 a circuit through the working contact and armature 1228 for relay 1204. Relay 1204 closes a locking circuit for itself at armature 1218, and at armature 1219 closes a circuit for the switch-through relay 1202 through armature 1216 and its resting contact. Relay 1202 operates and at armatures 1211 and 1214 disconnects conductors 1197 and 1199 from the windings of the line relay and connects them instead to conductors 1234 and 1235, at the same time disconnecting the latter conductors from the back bridge circuit of the trunk circuit. At armature 1212, the tuned relay 1201 is connected across conductors 1234 and 1235 in series with a condenser, and a circuit is closed at armature 1213 to maintain release relay 1207 energized independent of line relay 1206, which now falls back. The trunk circuit remains in this condition until the four-hundred-cycle current is received by the tuned relay 1201, with results to be described subsequently.

In the repeater R-2, Fig. 12, when relay 1109 falls back responsive to the switching-through operation of the trunk circuit TC-4, Fig. 13, it closes at armature 1129 a circuit for relay 1104, whereupon relay 1104 operates and closes a locking circuit for itself at armature 1116. At armature 1117, relay 1104 opens a point in the circuit of relay 1108 so as to prevent any further operation of this relay until the connection is released. At armature 1133, relay 1104 closes a circuit through armature 1114 and its resting contact for the switch-through relay 1102. Relay 1102 operates and at armatures 1110 and 1113 disconnects conductors 1097 and 1099 from the windings of the line relay and connects them instead to conductors 1130 and 1131, at the same time disconnecting the latter conductors from the back bridge circuit of the repeater. At armature 1111, relay 1102 connects the tuned relay 1101 across conductors 1130 and 1131 in series with a condenser, and at armature 1112 it closes a circuit from maintaining release relay 1107 operated independent of line relay 1106, which now falls back. The repeater R-2 remains in this condition until the tuned relay 1101 is operated by four-hundred-cycle current in a manner to be pointed out hereinafter.

In the director, the sending operation is started in the hereinbefore described manner responsive to the switching through at the repeater R-2, Fig. 12, and the call indicator impulses are transmitted over a metallic circuit through the repeater R-2 and the trunk circuit TC-4 to the call indicator in the called manual office.

When the director transmits the impulse of four-hundred-cycle current, after having transmitted the call indicator impulses, the tuned relays 1101, Fig. 12, and 1201 Fig. 13

both operate. Relay 1101, upon vibrating its reed in response to the current to which it is tuned, closes a circuit for relay 1103. Relay 1103 has its copper slug on its armature end so as to make it slightly slow to pull up. This is to prevent the relay from operating responsive to a single closure of the contacts of the relay 1101 in case the latter should operate in response to a foreign current surge. The copper slug on the relay makes the effect of the impulses cumulative, with the result that the relay operates after its circuit has been closed a few times by relay 1101. Upon operating, relay 1103 at armature 1114 opens the circuit of relay 1102 and closes a locking circuit for itself. Relay 1102 is slow acting so as to maintain the switched through condition long enough to insure that the tuned relay in the trunk circuit TC-4 has responded before the switched-through condition has been terminated.

After an interval, relay 1102 falls back and again connects up the line-relay and back-bridge circuits and opens the circuit of release relay 1107. Line relay 1106 now operates over conductors 1097 and 1099 and closes at armature 1121 the circuit of the release relay and again closes the back-bridge circuit at armature 1122.

In the trunk circuit TC-4, Fig. 13, relay 1203 responds when relay 1201 operates responsive to the four-hundred-cycle current. At armature 1216, relay 1203 opens the circuit of relay 1202 and closes a locking circuit for itself. At armature 1215 the said relay 1203 prepares a bridge across the conductors 1234 and 1235. A moment later, relay 1202 falls back and again connects up the conductors 1197 and 1199 to the windings of line relay 1206 and it opens at armature 1213 the circuit of release relay 1207.

When relay 1202 falls back, or when the line relay 1106 of the repeater R-2 pulls up, whichever is completed last, line relay 1206 operates over conductors 1197 and 1199 and again closes the circuit of release relay 1207 at armature 1224 before the said release relay has had a chance to fall back. At armature 1223, relay 1206 completes a bridge across conductors 1234 and 1235, which includes the normally closed contacts controlled by armature 1211, armature 1215 and its working contact, right hand winding of relay 1205 armature 1223 and its working contact, impedance 1208, and the normally closed contacts controlled by armature 1214. The closure of this bridge results in the reoperation of the line relay of the distant cord circuit in the usual manner.

When the connection has been completed and when a response has been secured from the called subscriber, the reversal in the current flow over conductors 1234 and 1235, brought about by the battery feed relay in the cord circuit, results in the operation of the elec-

tro-polarized relay 1205. At armature 1221 and 1222, this relay relays the reversal back to the electro-polarized relay 1105 of the repeater R-2, which latter relay makes a similar reversal at armatures 1119 and 1120.

When the calling subscriber replaces his receiver at the end of the conversation, the connection is released in the usual manner, the locked up relays in the repeater R-2 being permitted to fall back when release relay 1107 falls back, and the locked up relays of the trunk circuit TC-4, Fig. 13, being permitted to fall back when the release relay 1207 falls back.

What is claimed is:

1. In a multi-office telephone system containing an automatic office and a manual office, a call indicator in the manual office for indicating to the operator the number of called manual lines, a register sender for operating said call indicator, an automatic switch in the automatic office for trunking calls from said register sender to the manual office, a trunk line in the automatic office divided into two inductively coupled sections and included in said connections, means for holding said automatic switch operated over the first section of said trunk line, means in the automatic office controlled from the manual office for temporarily uniting the two sections of the trunk line conductively and for establishing a local holding circuit for said switch, means for then initiating the operation of the register sender to set the call indicator over the two sections of the trunk line in series, and means for subsequently restoring the trunk line to its initial condition and for opening said local holding circuit.

2. In a multi-office telephone system containing an automatic office and a manual office, a call indicator in the manual office for indicating to the operator the number of called manual lines, a register sender for operating said call indicator, an automatic switch in the automatic office for trunking calls from said register sender to the manual office, a trunk line in the automatic office divided into two inductively coupled sections and included in said connections, means for holding said automatic switch operated over the first section of said trunk line, means in the automatic office controlled from the manual office for temporarily establishing a local holding circuit for said switch and for altering the association of the two sections of said trunk line so that the sending of call-indicator impulses over the first section results in the transmission of the call indicator impulses over the second section of the trunk line, means for then initiating the operation of the register sender to transmit the necessary call indicator impulses to the first section of the trunk line, whereby they are transmitted over the second section of the trunk line.

line to set the call indicator, and means for subsequently restoring the trunk line to its initial condition and for opening said local holding circuit.

5. 3. In a multi-office telephone system containing both manual offices and automatic offices, a register sender including means for registering the called-office designation and the called-line designation when a call is made, automatic switching mechanism controlled by the register sender to extend the connection to a tandem manual office when the call is to be completed to or through such office, a call indicator in the said tandem manual office, said register sender being effective for controlling said call indicator to register and display the called-office and the called-line designation, and translating means in said register sender whereby the control exercised by the sender to set the portion of the call indicator that indicates the called office may be assigned at will.

4. In a multi-office telephone system containing both manual offices and automatic offices, a register sender including office-registering and line-number-registering apparatus for registering the called-office designation and the called-line designation when a call is made, automatic switching mechanism controlled by the register sender in accordance with the setting of said office-registering apparatus to extend the connection in certain cases to a tandem manual office, a call indicator in the said tandem manual office containing means for registering and displaying the called-office and called-line designations, sending means in the register sender, an auxiliary register in said register sender set in accordance with the setting of said office registering apparatus, means for operating the sending portion of said register sender under the control of said auxiliary register to set the portion of said call indicator that indicates the desired office and for operating said sender under the control of the line-number-registering apparatus to set the remaining portion of the call indicator, and a translator interposed between the office-registering apparatus and the said auxiliary register, whereby the setting of said auxiliary register in accordance with a given setting of the office-registering apparatus may be assigned at will.

5. In a call director for controlling the operation of automatic switches, a primary register and a secondary register, a sending switch for effecting the necessary control to set the automatic switches in accordance with the setting of said primary register, and means for operating said sender under the control of said primary register to effect a corresponding setting of said secondary register.

6. In a call director for controlling the extent of movement of automatic switches, two

primary registers and a secondary register, a sender controlled by the first primary register to effect the necessary control over said switches, and means for bringing said sender under the control of the second primary register to set said secondary register in a position corresponding to the setting of the second primary register.

7. In a call director for controlling the extent of movement of automatic switches, two primary registers and a secondary register, a sender controlled by the first primary register to effect the necessary control over said switch, means for bringing said sender under the control of the second primary register to set said secondary register in a position corresponding to the setting of the second primary register, a second sender in said director, and means for operating said second sender to effect a control in accordance with the setting of said secondary register.

8. In a call director, a plurality of registers and two senders, means for operating said registers to record a desired called number, means effective in one case for causing the first sender to operate in accordance with all the registered digits, means effective in another case for predetermining that the second sender will operate in accordance with the last portion of the registered number, said means being effective before the first sender has finished operating in accordance with the first part of the number, and means for continuing the operation of the first sender after the predetermining means has operated and until the first sender has finished operating in accordance with the remaining portion of the first part of the number.

9. In a call director for handling calls to automatic lines and to manual lines, a first sender for use in case the number is that of an automatic line, a second sender for use in case the number is that of a manual line, a plurality of registers for controlling the operation of either of said senders, means for starting the first sender responsive to the operation of the first of said registers in case the first sender is to operate, and means effective in case the second sender is to operate for initially starting the second sender only after all of said registers have been operated.

10. In a call director for handling calls to automatic lines and to manual lines, a first sender for use in case the number is that of an automatic line, a second sender for use in case the number is that of a manual line, a plurality of registers for controlling the operation of either of said senders, means for starting the first sender responsive to the operation of the first of said registers in case the first sender is to operate, means effective in case the call is for a manual line for signalling the manual operator only after all the registers have been operated, and means con-

trolled by the manual operator after she is signalled for starting the second sender.

11. In a telephone system including automatic offices and manual offices and in which call directors are employed in the automatic offices for controlling the setting up of connections from the automatic lines, said call directors being responsive to the receipt of the office designation to operate the necessary 5 automatic switches to trunk a call to the desired manual office regardless of whether or not the complete number is registered in the call director, the operator in the manual office not being signalled when the said call is so 10 trunked, and means in said call director for transmitting an impulse over the established connection when the last digit in the number has been registered, and means controlled 15 over the established connection responsive to 20 said impulse for signalling the operator.

12. In a telephone system, containing a plurality of offices, a link circuit in one office, a number register for registering called numbers, ringing-current-applying means included in said link circuit, and means associated with said register for controlling said ringing-current-applying means in accordance with the register settings so that the ringing current is applied only in case a 25 connection set up is a local connection.

13. In a multi-office telephone system containing two automatic offices and a manual office, registering and sending apparatus in the first automatic office, a call indicating device in the manual office, automatic switching mechanism in the automatic offices for setting up a connection from the first automatic office to said manual office via trunk lines connecting the first office with the second 30 office and connecting the second office with the manual office, the trunk line connecting the second office with the manual office being divided in the second office into two inductively coupled sections, means controlled over 35 the first section of said trunk line for maintaining the switching mechanism in the second automatic office operated, means effective after the connection has been set up to the manual office for closing a separate holding circuit for the mechanism in the second 40 automatic office and for altering the association between the two sections of said trunk line so that impulses may be transmitted over 45 both sections of said trunk line to set the call indicator in the manual office, and means for thereafter operating the sending means in the first automatic office under the control of the associated registering means to transmit over 50 the established connection impulses representing the instant registered telephone 55 number to the call indicator in the called manual office.

14. In a telephone system as claimed in 60 claim 1, a timing device, and means including

said timing device for controlling said restoring means.

15. In a telephone system as claimed in claim 1, a timing device for maintaining the automatic switching mechanism in the second 70 automatic office operated independent of control over the first section of said trunk line for an interval of time following the restoration of the trunk line to its original condition.

16. In a multi-office telephone system, a 75 trunk line outgoing from a first office to a second office, automatic switching mechanism in the first office for extending a connection to said trunk line, means individual to said trunk line for closing a holding circuit for 80 said switching mechanism subject to the maintenance of a current flow over said trunk line, means for stopping the current flow over said trunk line and for closing an independent holding circuit for said switching mechanism, and means including a timing device 85 for restoring said trunk line to its initial condition.

17. In a multi-office telephone system, a 90 trunk line outgoing from a first office to a second office, automatic switching mechanism in the first office for extending a connection to said trunk line, means individual to said trunk line for closing a holding circuit for 95 said switching mechanism subject to the maintenance of a current flow over said trunk line, means for stopping the current flow over said trunk line and for closing an independent holding circuit for said switching mechanism, and means including a timing device 100 for restoring said trunk line to its initial condition, and means including a further timing device for maintaining the holding circuit intact for an interval following said restoration.

18. In a telephone system, a line, a register sender, means for temporarily connecting said register sender to said line, said register sender including a multi-position sending-control device having a normal position, a 105 two-step relay device controlling the disconnection of said register sender from said line, means for operating said sending-control device through its several positions, means including a circuit closed by said device in its 110 position just preceding normal position for operating said relay device through its first step and for operating the device through its second step responsive to the opening of said circuit, and means including said relay device for stopping the operating of said sending-control device before the said device passes through its normal position.

19. In a telephone system, a line, a register sender for temporary connection to said 120 line, said register sender including two sending devices, means for operating one or the other of said sending devices when the register sender is taken into use, a combination one-step and two-step relay in said device for 130

bringing about the freeing of the same, and means whereby said relay is operated as a one-step relay in case one sender is used and is operated as a two step relay in case the other sender is used.

5 20. In a multi-office telephone system containing an automatic office, one or more manual offices reached through a tandem manual office, a separate non-tandem manual office, an automatic switching mechanism in the automatic office for extending a connection, according to its destination, to the proper manual office, call indicators in the manual offices reached from said automatic office, the indicator in the non-tandem manual office being arranged to indicate subscriber digits only and the indicator in the tandem manual office being arranged to indicate the office designation in addition to the subscriber digits, 10 said register sender including a multi-position sending control switch having separate positions assigned to each digit which it may transmit to the call indicators, means for advancing the switch through all its positions 15 to send call indicator impulses in case the call is to or through a tandem manual office, and means for causing said switch to automatically advance through the office-designating positions without sending impulses to the 20 call indicator in the called manual office in case the call is to said terminating manual office.

21. In a telephone system, a trunk line divided into two disconnected sections, the first 35 section terminating in one winding of a double-wound two-step relay device, means for operating said device through its first step over said one winding when the trunk line is seized, first-step contacts on said device for closing a shunted locking circuit through the 40 other winding of the relay, means for momentarily opening the initial circuit of the device to cause the same to operate through its second step, and second-step contacts on said 45 relay for disconnecting the first section of said trunk line from the device and for extending it to the said second section.

22. In a multi-office telephone system containing a plurality of automatic offices and a 50 manual office, trunk lines interconnecting said offices, a call indicator in said manual office, means including automatic switching apparatus in a first automatic office for setting up a connection over a trunk line to a second automatic office and for extending the connection 55 from the second automatic office over a trunk line to the manual office, a sending device in the said first automatic office, and means for operating said sending device to 60 transmit impulses directly from the first office through the second office to the call indicator in the manual office over the two trunk lines of the extended connection.

23. In a telephone system, an automatic 65 repeater associated with a two-section trunk

line and arranged to repeat impulses received over one section into the other section, means controlled over one section of said trunk line for cutting out the repeater and for joining the two sections directly together, and a timing device local to the repeater for bringing about the re-insertion of the repeater after an interval of time has elapsed.

70 24. In a telephone system, a trunk line comprising two inductively coupled sections, 75 means for joining the two sections of the trunk line directly together, and means including a timing device for limiting the time that the two sections may be joined together.

25. In a telephone system, a trunk line comprising two inductively coupled sections, means controlled over one section for joining the two sections of the trunk line directly together, and means including a timing device for limiting the time that the two sections 80 may be joined together.

26. In a telephone system, a trunk line comprising two inductively connected sections, means controlled over one section of the trunk line for connecting the two sections directly 90 together, and means subsequently controlled over the other section of the trunk line for disconnecting the two sections from one another.

27. In a telephone system, a trunk line 95 comprising two inductively coupled sections, means for connecting the two sections of the trunk line together, means for sending impulses of one character over the trunk line through the two sections in series, a relay 100 associated with said trunk line and non-responsive to the said impulses, means effective after all the said impulses have been transmitted for transmitting an impulse of a different character, said relay being responsive 105 to the last-named impulse, and means responsive to the operation of the relay when it responds to the last-named impulse for opening the direct connection between the two sections 110 of the trunk line.

28. In a telephone system, a bridge across a trunk line, means for removing said bridge and for transmitting a plurality of impulses of a given character over the two conductors of the trunk line in series, a relay associated 115 with said trunk line but non-responsive to said impulses, means effective after all of said impulses have been transmitted for transmitting an impulse of a character to which said relay is responsive, and means controlled by 120 said relay when it responds to the last named impulse for again placing said bridge across the trunk line.

29. In a call director arranged to handle 125 calls from automatic lines and intended for lines terminating in either a tandem manual office or in a non-tandem manual office, registering apparatus in the call director for recording the called-office designation and the called-line designation, automatic switches 130

operated under the control of the said apparatus in accordance with the office designation for trunking the call to a called manual office, a sender in said called director for transmitting to the called manual office the number of the desired line in accordance with setting of the line designating portion of the registering apparatus in case the call is for a terminating manual office, and for sending in addition an office designation in accordance with the setting of the office designating portion of the registering apparatus in case the call is to or through a tandem manual office, means for starting the operation of said sender dependent upon the complete registration of the number in case the call is to a terminating manual office, a secondary register controlling said sender to send out the office-designating indication when said indication is needed, said secondary register in turn being controlled by the office-designating portion of the first-named registering apparatus, and means for rendering the starting of said sender dependent upon completion of the operation of said secondary register when the same is to be operated.

In witness whereof, I hereunto subscribe my name this 16th day of July, A. D. 1926.

RUDOLPH F. STEHLIK.
